ABSTRACT OF THE DISCLOSURE

An apparatus for winding and cutting a predetermined length from a continuously fed web having a succession of like designs or indicia thereon such that the cut is in register with the design or indicia. A pair of web winding mandrels are rotatably mounted on a rotatable turret to receive the web after it has been printed; the turret being in turn mounted to index each mandrel between a starting position where the previous running web is cut and the rest of the web is started upon a fresh mandrel, a winding position where the major portion of the web is coiled upon the mandrel, and an unloading position where the finished coil is removed from the mandrel. The mechanism of the apparatus is driven through a plurality of interconnected planetary drive systems such that the feed of the web upon the mandrel is synchronized with the input from the press upon which the web is being printed, with the movement of the turret upon which the mandrel is mounted, and with an enveloper mounting the web cut off mechanism; such that these various mechanisms are driven in synchronism with each other. The web winding mandrels are formed in two sections each with cooperating cam surface biasing substantially the longitude and the length thereof with one section mounted for slidable movement upon the other along the cam surface, with both sections normally forming opposed circular sections of a given diameter, and with both sections cooperating with means operable upon operation of the turrets to a given index positions for displacing same along the cam surface to reduce the diameter of the sections. Appropriate electrical circuitry is provided to facilitate the operation of the various elements of the mechanism and for providing a count to signal and control operation of the cut off mechanism so as to precisely cut the web between successive indicia.

BACKGROUND OF INVENTION

This invention relates to improvements in apparatus for the slitting and winding into coils a relatively wide web of paper or other sheet material into a number of relatively small and narrow rolls. More particularly, the invention provides improved means and method for automatically winding upon an arbor or mandrel a plurality of web strips, such as well known trading stamps, to form a plurality of rolls thereof comprising in length a predetermined number of stamps and in which any roll may be of a preselected number of stamps in width.

Where webs characterized by repeated impressions, such as trading stamps or the like, are to be formed in continuous manner into separate rolls having a preselected number of stamps to the roll a problem is presented, in that, not only is suitable control and counting means required for determining when a proper number of stamps are wound to complete the roll, but also special means are required capable of severing the web at a precise impression junction in separating a final stamp of the completed roll from the first stamp commencing a new roll.

An object of the present invention is to provide im-

2

proved means for automatically winding a web to continuously form rolls of predetermined size and which are accurately cut off at a precise count line.

Another object is to provide means for forming successive rolls of web of a predetermined size without interrupting the winding operations.

Another object provides means for effecting continuous coiling operations to a web which may enter the coiler in either an intermittent or continuous feed manner.

Further, the invention includes means for automatically modifying the speed of the winding machine to thereby correct an advancing speed of the web to synchronize with the web feed speed as entering the winding machine.

Another object of the invention is to provide improved cut-off devices which in a continuous web feeding operation accurately sever the web ribbons on the fly and direct the severed ends thereof about a new mandrel.

Another object is to provide control means for determining operation of the severing means in accordance with a preselected number of stamp counts comprising a complete roll.

A further object includes means for synchronizing a web cut-off movement of the severing means to the surface speed movement of the web.

Special ribbon spreading means are also provided for separating longitudinal edges of adjacent webs incident to web slitting operation.

As another object the invention provides control devices timing the severing operation to effect an accurate cut-off of the webs relative to any given line separating a stamp impression from a succeeding stamp impression along the web.

As a further object the invention includes in the timing control a means operable as timed by the web in accordance with a perforated pattern therein whereby to count the number of stamp impressions comprising a roll and to determine exactly where the web must be cut off.

Yet another object of the invention provides improved spindle means for winding the web and which permits an easy removal of a completed web roll therefrom.

Still another object provides for mounting the spindle upon a turret adapted to be indexed to successive control positions for displacing a completed web roll to a take-off position and for bringing a new spindle into position for receiving the incoming web.

The invention also provides special means for constantly maintaining surface speed of the web substantially uniform throughout the roll winding operations.

As a further object the invention includes means for maintaining winding surface speed of the web constant during any displacement of the web roll spindles incident to indexing movements of the turret support therefor.

These objects, and such other objects as will herein-after appear, will become apparent from the following description of preferred embodiments of the present invention as shown in the accompanying drawings, in which:

FIG. 1 with 1A comprise a front elevation view of the coiling machine and showing the web path therethrough;

FIG. 2 is a rear elevation view of the coiling machine and showing the various drive trains;

FIG. 3 is a detail front elevation view of the turret and showing drive means for the winding spindles;

FIGS. 4 and 5 are detailed views of the pin cylinder operated by the web;

FIG. 6 is a fragmentary sectional view taken on line 6 of FIG. 1, and showing web diffusing devices associated with the web slitting means;

FIGS. 7 and 8 are detail views of a novel device for effecting web drag;

FIG. 9 is a detail view of the dancer web tensioning device;

FIG. 10 is a detail view of the web strip tension means;
FIGS. 11 and 12 are perspective schematics showing the differential devices included in the drive train;

FIG. 13 is a detail view of a novel spindle for winding the web;

FIG. 14 is a detail cross section of a ball type integrator in the drive for the spindle, taken on line 14—14 of FIG. 3;

FIG. 15 taken as a whole comprises a detailed perspective of the spindle shown in FIG. 13;

FIG. 16 is a right end view of the said spindle;

FIGS. 17 to 20 are detailed views of the ball drive integrator of FIG. 14;

FIG. 21 is a section through the web cut-off and enveloper devices;

FIG. 22 is an enlarged detailed sectional view of the web cut-off knife secured to the forward member of the enveloper devices;

FIGS. 23 to 25 are detailed views showing the web cut-off knife and enveloper devices advanced in various steps of its movement;

FIG. 26 is a fragmentary top plan view of the enveloper devices;

FIG. 27 is a detail of said devices taken on line 27—27 of FIG. 26;

FIG. 28 is a front view of the devices shown in FIG. 22;

FIGS. 29 and 30 are detailed plan and end views respectively of the web roll follower devices;

FIGS. 31, 31A—31D comprise a schematic of the pneumatic and electrical circuit control for the machine; and

FIG. 32 illustrates the arrangement for FIGS. 31—31B.

IN GENERAL

The coiling machine of the present invention is designed for slitting and rewinding into separate adjacent coils of various widths a web of standard size trading stamps; which normally include twenty stamps across the web.

The machine may be used for "off-press" work wherein a web may be fed in a continuous manner from a parent roll or may form an attachment to any of the well-known stamp printing and perforating machines, which may include intermittent feed means and any suitable counter mechanism, such as the well-known "Veeder" counter disclosed in U.S. Patent No. 2,799,740 issued July 16, 1957 to F. T. Blackman and U.S. Patent No. 2,628,799 issued Feb. 17, 1953 to H. N. Bliss, to effect a count for each printing stroke corresponding to a ten stamp impression processed along the web during each cycle of machine operation.

In the illustration given, and with particular reference to FIGS. 1—1A and 9 for an initial webbing up operation the web W enters the coiler through a "dancer" comprising spaced tension control arms 1 fast on a shaft 2 pivotally mounted upon the framing 3 of the coiler machine. Supported for rotation upon the distal end of movable arms 1 are three spaced rollers 4, while pivoted upon a fixed bracket 5 (FIG. 1A) is a pair of spaced rollers 6. For "off-press" work, where web W is drawn off a suitable storage drum in a continuous manner, the web is fed beneath rollers 4 and up over an idler roller 7 mounted upon the pivot shaft 2 of dancer arm 1. For "on-press" work, in which the web is fed to the coiler in intermittent manner from a press, the web is first wrapped successively around the rollers 4 and 6 as shown in FIG. 1A and thereafter up over the roller 7.

A light infeed web tension between the press and the coiler may be attained by attaching a suitable spring 7' (FIG. 9), of more or less force as required, to the dancer shaft 2. The dancer 1 is limited to a short oscillating excursion sufficient for operating a pair of micro switches S10 and S11 controlling a "jogging" or correction motor 40 (FIG. 11) which speeds up or slows down the coiler so that it will stay in step with the press machine. When

the coiler winds faster than the press delivers the web the upstream correction switch S10 is operated by the dancer 1 and motor 40 operates in a direction to slow the coiler down. On the other hand if the dancer operates the downstream switch S11, the correction motor runs in a direction to speed up the coiler. The correction motor 40 runs only long enough for the coiler to again be brought into synchronism with the press.

To initially thread the coiler about ten to fifteen feet of leading web is preliminarily advanced from the press to the dancer 1. Then from the dancer the web W is threaded around a guide roller 8 (FIG. 1) clockwise, thereafter from the bottom up counterclockwise around a tension drag roller 9, clockwise around a guide roller 10, around a portion of a cylinder 11 having pins 12 for engaging suitable perforations of the web, over the top of a guide roller 13 for holding the web around pin cylinder 11, under an input roller 14 associated with a web slitting assembly, thereafter between the slitting knives 16 and associated score cylinder 17 of said assembly, now around a special convex ribbon diverging output roller 18 of the slitter assembly, past suitable ribbon tension equalizing shoes 19, around a concave roller 20 for spreading the ribbons, over the top of a ribbon spacer guide roller 21 mounted for clockwise rotation upon a turret 22 which is supported for counterclockwise rotation upon shaft 23, and thence over the top of a spindle 24 and a fixed rod 25' in the turret 22, and on to a second spacer guide roller 21 and spindle 24'.

Associated with each spindle 24, 24' is a follower roller 25, mounted on a corresponding arm 26 pivotally mounted at 27 upon turret 22 and connected by link 28 to a spring tensioned arm 29, pivoted upon the turret at 30. By lifting the related follower roller 25 the web may be manually wrapped around spindle 24' and after releasing the follower the spindle may then be power driven counterclockwise to wind a few turns of web thereon by special "jog drive" controls operating motor 40 (FIG. 11), as in the manner and purpose hereinafter described.

During the above initial webbing up operation the slitter knives 16 are usually withdrawn, so that the coiler is now webbed up and ready to run with a full or unslit web. The slitting assembly is of well-known design and it is sufficient at this time to say that a desired number of knives 16 are inserted to accord with the number of stamps to the width of each coil to be simultaneously wound upon spindle 24'.

As will become more apparent as the description proceeds, the intended mode of operation is to automatically start the winding of any new roll upon the upper spindle 24 during a completion of a preceding roll upon the lower spindle 24'. Special cut-off means being provided for automatically severing the web at a precise point separating indicia on a new roll from the old, in accordance with the manual setting of a preset count control means for determining the desired number of stamps required for the completed rolls.

Following such severing of the web, lower spindle 24' continues only a few more turns and will then stop, while upper spindle 24 will continue in its winding operation. Thereafter turret 22 is caused to be automatically rotated in a counterclockwise indexing operation, bringing spindle 24' from the "winding" position indicated in FIG. 1 to an intermediate position indicated as the "unloading" position in said figure. Thus at this point in the webbing up operation an operator now removes the partially completed roll and immediately engages a control switch which causes the turret 22 to again rotate until the upper spindle 24 is brought to the "winding" position while the spindle 24' is moved to the upper starting or "cut-off" position ready for receiving a new roll of stamps.

After the above initial webbing up operation a number of preliminary short coiling runs may be made for checking and to make any necessary adjustments and if the

running and counting functions operate normally the coiler is then ready for production running.

Differential system for positive drive
(FIGS. 1, 2, 11 and 12)

As earlier stated it is required herein that the web be separated along a precise line of demarcation between two stamps. Therefore, it is necessary that the various devices of the coiler which in any way control movement of the web be synchronized with operations of the machine which prints and perforates the stamps. Also, such synchronized movement of the web during winding operations thereof upon spindles 24, 24' must be maintained even during indexing operations of the turret 22. Again the web cutoff devices (herein termed the enveloper) must be timed to act in precise synchronism with the surface movement of the web during the severing operation. The present invention accomplishes the above through the novel arrangement of a series of differential gear systems providing positive interlocking drive means, as in the manner hereinafter to be described.

As is well known, a mechanical differential is a geared device for adding or subtracting the rotation of two or more input shafts in a manner so that the output shaft thereof is always the algebraic sum of the rotations of such input shafts. In the instant case the drive system gearing performs three separate functions centered around one of the three differentials indicated as 1st, 2nd, and 3rd in the diagrammatic showing (FIG. 11). Also a 4th differential is included, as indicated in the diagram (FIG. 12), which relates to the turret indexing drive.

With particular reference being made to FIGS. 1 and 11, the main input drive shaft 35 of the coiling machine has drive connection, through means of a well-known combination magnetic clutch and brake unit 36, 36', with a shaft 37 extending from any suitable stamp press machine. Said drive connection however where different speed operations are desired may also include shaft 38 and a change pulley belt 39. The clutch-brake unit 36, 36' provides means whereby the coiler may be jogged independently of the press, or so that the press may be operated independently of the coiler. Clutch 36 is between the press and the brake 36' so that the brake will be applied to the input shaft 35 between the clutch 36 and the coiler. As hereinafter to be described, electrical circuits control the clutch-brake unit in a manner so that when clutch 36 is engaged to couple the coiler to the press the brake is released and when the clutch is disengaged the brake is applied. Said brake being needed to hold input shaft 35 stationary so that input operations of the "jogging motor" 40 upon a second leg of the first differential system will act to operate the coiler devices rather than merely acting to cause a backward rotation of shaft 35.

As more fully to be described with reference to the circuit diagram (FIG. 31), both the clutch 36 and the brake 36' have step energization circuits in their field control to prevent jerk starts and stops. These step circuits apply only partial field current for a limited time duration to cause a partial clutch or brake action so that the coiler will have an acceleration or deceleration period before the full clutch or brake drive is applied.

Fast upon the opposite end for rotation with shaft 35 is a bevel gear 41 (FIGS. 1 and 11) meshing in 1:1 ratio with a bevel gear 42 fast for rotation with a shaft 43 comprising one input leg of the 1st differential assembly. Fast upon the opposite end of shaft 43 is an input gear 44 meshing in 1:1 ratio with a planet gear 45 fast for rotation with a sleeve 46 supported upon a stud shaft 47 secured in a gear 48 loosely mounted upon the shaft 49. Said shaft is supported at one end by well-known needle bearing means mounted within the input gear 44 and at its opposite end being supported by a double row ball bearing in a removable support plate 51 (FIG. 2). Fast for rotation with sleeve 46 (FIG. 11) is a planet gear 52

5

meshing in 2:1 step down ratio with a sun gear 53 fast for rotation with shaft 49.

Meshing with gear 48 is a drive worm 54 fast upon one end of a shaft 55 driven by the correction motor 40. Thus shaft 49 forms an output leg of the 1st differential and may be rotated according to the summation of the two input legs, as imparted by the combined rotations of the two input shafts 35, 55 (FIGS. 1, 2 and 11).

The whole purpose of the 1st differential is to allow a correction rotary motion of the jogging motor 40 to be added to or subtracted from the net driving revolutions of the press drive shaft 37 coupled to the coiler shaft 35. The correction motor 40 can be driven in the forward or reverse direction to correct for any inaccuracy between the feed-up of the press and the wind-up of the coiler spindles 24, 24'. If the coiler winds more slowly than the press feeds the web the correction motor can rotate in a direction to add its rotation to that of the press drive rotation so that the output shaft 49 of the 1st differential turns faster and the winding is speeded up. If the coiler winds faster than the press feed up, the reverse occurs.

When the correction motor 40 is not running, the coiler drive is through gear 44 to gear 45, then through gears 52, 53 to the differential output shaft 49 which from the stated gear ratios would thus operate at one-half the press input speed. Therefore if the press shaft 37 required three revolutions relative to each impression operation of the press, the shaft 49 would operate for one and one-half revolutions.

30 The worm gear 48 operated by worm 54 has also a 2:1 reduction drive to the output shaft 49 through the gearing 44, 45, 52, 53 which operate as planetary gearing in the correction drive for the spindles 24, 24'. Worm gear 48 must rotate three revolutions to produce a coiling wind-up corresponding to one impression. Therefore, three revolutions of worm gear 48 will advance or retard the coiling wind-up equivalent to one impression while producing one and one-half revolutions of output shaft 49 either added to or subtracted from those produced by the press drive, according to the direction of operation of correction motor 40, as hereinafter will more fully be described.

35 Torque from the correction motor 40 will produce motion of the output shaft 49 or of the input shaft 35 depending upon which has the least resistance to motion. Therefore without the brake means 36' on the input shaft 35 earlier set forth said shaft would have the least resistance and so it would erroneously revolve, instead of the coiler drive mechanism as is required in any jogging operations by motor 40.

40 To prevent the correction motor shaft 55 from drifting and being driven by the torque of the main press drive a similar magnetic control air brake 56 is also associated therewith, in which the field circuit is arranged in the manner hereinafter described so that when either the forward or reverse air valves are operated the field circuit is broken and the brake releases, allowing the correction means to run free. When the air valve is released, then the brake is reapplied to stop and hold the shaft. Also, any suitable flywheel means may be applied to shaft 55 to prevent the correction means starting with a jerk which would introduce an unwanted tension surge upon the web.

45 Fast for rotation with the differential output shaft 49 is a gear 57 meshing in 1:1 ratio with a gear 58 fast for rotation with a shaft 59. Said shaft 59 serves in the manner to be described as the drive means for the drag clutch 9 (FIGS. 1 and 2), the slitter knives 16, idler guide rolls 20, 21 and the spindles 24, 24'. Shaft 59 also serves as the main drive for a differential means associated with the turret indexing operations, referred to earlier in the specification, and to be more fully described hereinafter with respect to certain illustrative examples of coiling control operations. It will thus be noted that the devices driven from said output shaft 49 of the first differential are main-

tained in synchronism with the press through the action of the press output shaft 37 and the correction motor 40.

The output shaft 49 of the first differential also carries a gear 60 having 62 teeth for meshing with a ring gear 61 of 110 teeth and which comprises one input leg for the second differential means as indicated in the diagrammatic disclosure of FIG. 11. Ring gear 61 is loosely mounted for rotation upon shaft 62 of the output leg of said second differential and carries a stub shaft 63 upon which is rotatably mounted a sleeve 64 having secured thereon a pair of planetary gear members 65, 66. Planetary 65 has 25 teeth and meshes with a sun gear 67 fast for rotation with output shaft 62. The planetary 66 meshes in 1:1 ratio with a gear member 68 secured to one end of a sleeve 69 loosely mounted upon shaft 62. On the opposite end of sleeve 69 is a gear 70, with 50 teeth, for engagement with a four thread worm 71 secured to the lower end of a shaft 72 extending downwardly from a servo mechanism unit 73 of the well-known "Humphrey Drive" type. The "Humphrey Drive" unit 73 includes a leftwardly extending shaft 74 having a pinion 75 thereon of 30 teeth meshing with similar intermediate gearing connection 75' engaging a gear 76 of 105 teeth, said gear being fast for rotation with the output shaft 49 of the first differential means earlier described.

From the above it will be obvious that gear 60 on output shaft 49 of the first differential, through gear 61, serves as a first input drive leg to the second differential and that gear 76 on shaft 49 with gearing 75, 75' will act as the input drive to the "Humphrey" variable speed drive unit 73. The output shaft 72 of said unit provides a second input leg for the second differential, through the planetary gear train of said differential above described. The speed and direction of the "Humphrey" variable speed unit is controlled by a servo regulator mechanism in accordance with operations of a control arm 77, so that add or subtract motions therefrom may act to modify the operations of output shaft 62 of the second differential, in the manner and purpose to be described.

Fast upon one end of the output shaft 62 of the second differential is a pulley wheel 78 having positive belt drive connection 79 (see also FIG. 2) with a pulley wheel 80 fast for rotation with a shaft 81, suitably bearinged within the machine framing. Mounted fast upon shaft 81 for rotation therewith is a circular plate 82 having grooves cut therein to form cooperating positive motion cams 83, 84, herein termed the "enveloper" cam, within which a roller 85 of an arm 86 cooperates for rocking a shaft 87 in operating the web severing knife, or "enveloper" devices of earlier reference and to be more fully described hereinafter.

The purpose therefore of the second differential is to drive the enveloper cam in synchronism with the above-described input drive and to provide a way to add or subtract motion thereto from the "Humphrey" variable speed drive, whereby to keep operation of the said cam in exact synchronization with the surface speed imparted to web W by shaft 59 in the output drive of the first differential. Also, at the same time provide for correction of any variation as might occur in the operation of suitable control means to be described, which modify the speed of the web spindles 24, 24' in accordance with an increasing size thereof during coiling operations.

It may be noted at this time that with the above-described gear ratios if the correction input worm 71 and gear 70 are locked, the principal input gear 61 would drive the output shaft 62 and thus also enveloper cam plate 82 approximately 15% faster than the speed that would be synchronous with the web. To bring the output shaft 62 down to synchronous speed, the correction input gears 71, 70 rotate continuously to drive said shaft about 15% of synchronous speed in the reverse direction. Therefore, the two motions from the principal input and the correction input add algebraically to produce synchronous speed in

the output shaft. The correction input is controlled by means of the arm 77, having link connection 88, with the "Humphrey" drive unit 73, whereby to vary the correction input speed above and below the minus 15% synchronous speed value to accommodate for slight feeding variations of the web, as will now be described with reference to the third differential means.

The output shaft 62 of the second differential has fast thereon also an 80T gear 89 meshing with a 160T gear 90 loose on output shaft 91 for the third differential. Gear 90 is one input for the third differential, and serves to give to said differential continuous information as to the exact angular position of the second differential output shaft 62 and thus also the exact angular position of the enveloper cam plate 82. The third differential may therefore act on this information and by controlling the "Humphrey" drive in accordance therewith correct the position of the second differential shaft 62 if it is out of phase with the web, as in the following manner.

It will be recalled that in the initial webbing-up within the coiler for winding upon the spindle 24', the web W is threaded around a pin cylinder 11 having teeth 12 for engagement with suitable perforations of the web. Thus, during a coiling operation cylinder 11 is rotated in time with the surface movement of the web. Fast upon support shaft 92 for rotation with said pin cylinder is an 80T gear 93 (FIGS. 1, 4 and 11) having engagement with a 160T gear 94 comprising a second input leg to the third differential. Integral for rotation with gear 94 is a 72T gear 95 meshing with a 36T planet gear 96 which is integral with a 54T planet gear 97 meshing in 1:1 ratio with a sun gear 98 fast upon support shaft 99. The compound gears 96, 97 are loosely mounted for rotation upon a stud 100 supported by a spider arm 101 bearinged for rotation upon a short shaft 102 supported at each end respectively within a suitable recess of sun gear 98 and a corresponding 54T sun gear 103 fast to the output shaft 91 of the differential. Output gear 103 meshes in 1:1 ratio with planet gear 104, rotatable on stud 100, and including a 36T gear 105 integral therewith which meshes with the 72T gear member 106, fast with input gear 90 earlier set forth. Secured upon the shaft 99 is a 40T gear 107 (FIGS. 1 and 11) meshing with a single thread worm gear 108 fast upon one end of a rod 109 provided at its opposite end with a graduated finger knob 110. Rod 109 and worm gear 108 normally hold gear 107 and shaft 99 locked against rotation, but upon manual rotation serves as yet a third input leg whereby to adjust the third differential, in the manner and purpose to be described.

It is the function of the third differential to compare the speed and position of the web running on the pin cylinder 11 with the speed and position of the enveloper cam means 83, 84 (FIG. 2) operated from the output shaft 62 of the second differential and which control the web cut-off. Thus it is observed that the third differential has two principal inputs, one driven by means of shaft 62 of the second differential and the other by means of shaft 92 operated by the web W through pin cylinder 11 and that both said inputs operated at the same speed and in phase. The third differential is arranged so that these two input motions subtract within it and only the difference in speed or phase appears at the output shaft 91. Therefore, as long as the two inputs are at exactly the same speed and phase the output shaft 91 remains absolutely stationary. If for any reason one input should drop behind the other in angular position then the output shaft 91 will change angular position a corresponding amount, but remain stationary in that position. The arrangement being such that whenever the enveloper cam means 83, 84 happens to lag behind the web then differential output shaft 91, together with the control arm 77 thereon, is caused to be rocked clockwise (as viewed in FIG. 11). In like manner, should said cam means happen to run ahead then shaft 91 and arm 77 is rocked in a counterclockwise direction, the overall movement of arm 77 however being restricted between suitable

stop pins 111'. The operations of arm 77 thus acts to regulate the "Humphrey" variable speed device 73 in manner so that when the enveloper cam means 83, 84 lags relative to the web position it is speeded up to be brought back into proper phase with the web. In like manner should the cam means lead the web it will be slowed down to bring it back into phase therewith.

In addition to the above described means of maintaining the enveloper cam means 83, 84 synchronized with the web, special means are provided for adjusting the cam position to determine the exact point at which the cam will cause the cut-off means to sever the web along the line separating any stamp from another. This is accomplished by means of the third input leg to the third differential as operated by the manual control knob 110, above described. This knob may be suitably graduated to represent a given control movement corresponding to a given correction movement of the web, for example, each graduation could represent $\frac{1}{64}$ " of web movement, and may rotate the input worm 108 any number of turns. Thus if the enveloper cam means 83, 84 is either leading or lagging a desired cut-off position on the web this input acts to advance or retard said cam means for bringing the other two input legs of the third differential, as controlled by gears 93 and 89 respectively, into exact phase.

The motion ratio between the web pin cylinder 11 input and the differential output shaft 91 is such that if the other input legs of the differential, as represented by gears 107 and 90, are locked, one revolution of the pin cylinder 11 would produce one revolution of said output shaft. Likewise if input gears 93 and 107 are locked then one revolution of the enveloper would act back through the second differential gear 89 and the gear 90 to also produce one revolution of output shaft 91. These ratios being important in keeping the pin cylinder and the enveloper cam means in phase and so allow the pin cylinder to be rotated any number of times freely in either direction for obtaining proper mesh with the web during the initial webbing-up procedure while the coiler is stopped, as in the manner earlier set forth. Since it is necessary that output shaft 91 must be free to be rotated with manual knob 110 at such times, any suitable well-known ball slip type locating clutch means may be inserted between said shaft and the control arm 77 for the "Humphrey" drive unit 73, as illustrated at 111 (FIG. 11). As shown in FIG. 1, a lock clamp means 112, controlled from a thumb knob 113, is also provided to secure the shaft 109 and input gears 108, 107 in fixed position following any adjustment above described.

Webb winding spindle drive system (FIGS. 1-3 and 11-14)

The winding spindles 24, 24', referred to earlier in connection with FIG. 1 pull the web W through the coiling machine and therefore must develop the torque and variable speed to wind the coils with uniform tension and in step with the press means.

Since the web roll will constantly increase in diameter during a coiling operation, it is apparent that the surface speed thereof would likewise keep increasing unless correcting means were provided. For this purpose the following special means therefore are included herein.

As shown in FIG. 2 and diagrammatically illustrated in FIG. 12, the output shaft 59 of the differential means described with reference to FIG. 11 has positive drive connection, by means of a drive chain 114 engaging a 25T sprocket wheel 115 fast on said shaft, with one input leg of a fourth differential means including a 60T sprocket wheel 116 secured to one end of a sleeve 117 loosely mounted for rotation upon the turret support shaft 23 for the web winding spindles 24, 24' (FIG. 1) of earlier reference. Upon the opposite end of sleeve 117 is secured a 65T sun gear 118 meshing with a 30T planet gear 119 supported for rotation upon a spider arm 120 of the differential. Integral with planet gear 119 is a 50T

planet gear 121 meshing with a 45T gear 122 fast to the said drive shaft 23. Upon the opposite end of shaft 23 is secured a 64T bevel gear 123 having engagement with a pair of 48T bevel gears 124, 124', as shown also in FIGS. 3 and 14.

Each of the winding spindles 24, 24' has its own drive mechanism operable by the respective bevel gears 124, 124' independently of the other in the matter of speed of rotation. For each spindle the drive from shaft 23 through said gears is imparted to a related drive cylinder member 125, 125' of a ball type integrator device, adapted to control the speed of the respective spindles 24, 24' whereby to maintain a uniformly constant surface speed of the web throughout the winding or coiling operations thereof upon said spindles, as in the following manner.

It is recalled and as hereinafter more fully described, that the two winding spindles 24, 24' are supported upon a turret 22 rotatable upon support shaft 23 to bring each spindle successively to three functional positions: (1) the cutoff or starting position where the running web is severed and coincident with such operation is caused to be attached to the fresh spindle, (2) the winding position where the major part of the coil is wound, and (3) the unloading position where the finished coils are removed from the loaded spindle.

The above described cylinders 125, 125' related to the respective winding spindles 24, 24' are each suitably bearinged within frame means 126 (FIG. 3) which are mounted upon a rear plate 22' of the rotatable turret 22.

Cylinders 125, 125' constitute the input means of a well-known ball type integrator mechanism, which include a ball cage 127 (FIGS. 14 and 18-20) slidable along a pair of parallel bars 128, also mounted within the frame means 126. Mounted within said cage 127 is a pair of ball members 129 in contact with each other and arranged so that one ball engages the associated cylinder 125, 125' while the other is in engagement with a related circular plate 130, bearinged for rotation within rear plate 22' of the turret 22. Suitable compression springs 131 serve to pressure the balls between each corresponding cylinder 125, 125' and its associated plate 130. Plates 130 each have integral therewith a 36T gear 132 meshing with a 72T gear 133 (FIGS. 3 and 13) fast for rotation upon the related support shaft 134 for the respective winding spindles 24, 24' earlier set forth with reference to FIG. 1.

It will be recalled that associated with said spindles are feeler arms, such as the arm 26, which during a web winding operation will be rocked in a clockwise direction (FIG. 1) in accordance with an increasing diameter of the web roll. Said operation of feeler arm 26, through link 28 and arm 29, imparts also clockwise operation to a shaft 30 (being counterclockwise as viewed in FIG. 3).

As shown in FIG. 3 said shaft has fast thereon an arm 135 connected at 136 to a link 137 in turn pivotally connected at 138 (FIG. 19) to the related ball cage 127. The speed of the winding spindle may thus be controlled by the position of the driving balls 129 on the drive disc 130. The described linkage and the ball drive parts being proportioned so that the spindle will always turn at a speed to keep the periphery of the web coil at a constant speed and in step with the press. That is, when the coil has just been started and is of small diameter the spindle turns fastest but will be slowed in inverse proportion as the coil gains in diameter. A suitable spring member 31 (FIG. 1) urging follower roller 25 of arm 26 against the web roll serves to restore ball cage 127 in the opposite direction. The ball drive cylinders 125, 125' it is recalled are driven directly by the turret shaft 23 (FIGS. 12) operated through the differential devices earlier described at a speed constant and proportional to the press speed at all times. The drive balls 129 move axially along the corresponding cylinder 125, 125' and radially on the associated disc 130. Said balls being stacked and held in their respective cages one atop the other between the cylinder and the disc. With the rotating speed of the cyl-

inder constant the speed of the spindle is therefore determined by the radial position of the drive balls on the related disc 130 as in the manner above set forth. Two balls are provided in each case so that the respective cage may be positioned or moved when the corresponding drive cylinder and disc are stationary.

It is intended that after a winding spindle 24, 24' is indexed to the "unloading" position it shall be stopped and held against rotation in order that an operator may remove the web roll from the spindle. For this purpose each of the ball drive cylinders 125, 125' fast with the respective operating shafts 140, 140' include also a section 126' loosely supported on said shafts. The latter section of each cylinder however is held stationary by means of a brake shoe 141, as shown in FIG. 17. Thus as an increasing web roll advances the active ball cage 127 (FIG. 18) the balls 129 therein move toward the outer edge of disc 130 and also toward the stationary section 126' of the corresponding active cylinder 125 or 125'. However, to permit removal of a web roll, the present invention provides special means for completing a movement of the active ball cage during indexing operations of the turret 22 incident to bringing the web roll to the unloading position. Said means acting to bring the balls 129 upon the braking section 126' for stepping and holding the web and its support spindle 24 or 24' stationary, as in the following manner.

Secured to the main framing of the machine by means of bolts 142 (FIGS. 2 and 3) to extend around a portion of the circumferential edge of the turret plate 22' is a cam member 143. Fast upon the control shaft 30 for each ball cage 127 above described is an arm 144 having a roller 145 thereon cooperable with said cam member 143 in manner so that when turret 22 indexes to the web unloading position roller 145 engages edge 143' of cam 143 and moving under the cam will impart a counter-clockwise movement FIG. 3 to the said control shaft 30. This will lift the follower roller 25 (FIG. 1) away from the web roll on spindle 24' and at the same time move cage 127 (FIGS. 14 and 18) sufficiently to position balls 129 with the brake section 126' and so stop the spindle drive operation of plate 130. During a subsequent operation of turret 22 hereinafter described the spindle 24' is displaced from the unloading to the combined cutoff starting position. During said operation roller 145 runs along the inner edge of cam 143 and thereby maintains the braking action above set forth until the parts are restored under influence of spring 31 (FIG. 1) and a suitable gravity weight 32 (FIG. 3), as roller 145 is gradually released from restraint of the outwardly flared end 143' of the cam 143.

Compensation of spindle speed for turret indexing

It will be recalled that with turret 22 stationary, operation of the spindle drive shaft 23 (FIG. 12) from the output shaft 59 of the first differential means is effected directly through an input gear train 116-122 of a fourth differential mechanism. In order that web velocity through the machine will remain constant, regardless of any rate at which the turret may index, the drive for spindle operating shaft 23 includes a second input means for the said fourth differential mechanism. This second input means comprises a 72T sprocket wheel 146 (FIGS. 2 and 12) attached to the spider 120, supporting planetary gears 119, 121 as earlier described. Sprocket 146 has chain drive connection 147 with a 60T sprocket wheel 148 fast for rotation with a shaft 149, suitably supported within the fixed subframing of the machine. Fast for rotation with shaft 149 is an 18T sprocket wheel 150 connected by means of a chain drive 151 to a 10T sprocket 152 operated by a motor 153, through means of interposed 96T and 16T drive gears 154, 155, as shown. Drive chain 151, passing around an idler gear 156, engages the teeth of a 112T sprocket wheel 157 fast to the plate 22' of the indexing turret.

From the above it will be apparent that any operation of motor 153 in operating input sprocket wheel 157 of the fourth differential so as to index the turret 22 will also simultaneously therewith operate the sprocket and chain means 148, 147 to drive input sprocket 117 of said differential and thereby rotates the planetary spider 120 supporting planetary gears 119, 121, previously described.

The rotation of planetary gear support spider 120 is designed to introduce into the spindle drive shaft 23 a reverse operation which will subtract from the forward drive of said shaft a motion in proportion to the turret indexing rate. As a matter of fact if the main spindle drive input 116 is held stationary and the turret is indexed, the spindles would be caused to rotate backwards and unwind at a rate allowing for the turret to index without effecting any pull to the web. Without this mechanism the web velocity through the machine would rise as the turret indexed, resulting in changes to the web tensions and a disruption of the timing relationship between the coiler and the press. The differential arrangement described, however, combines the main spindle drive motion and the compensating drive motion to give smooth coiling and uniform web velocity during any turret indexing cycles. Turret indexing occurring in manner hereinafter to be described with reference to certain specific examples of the control mechanism set forth in connection with the wiring diagram of FIGS. 31, 31A-31B.

Web cutoff and "enveloper" (FIGS. 1, and 21-28)

30 The device as herein termed the "Enveloper" cuts the web and also envelopes the incoming end of the web around the empty spindle 24 (FIG. 1) to start a new coil. It comprises a series of hollow bars 158 extending transversely of the web path and is supported and coupled together by means of roller chain links 159 at each end thereof. Links 159 roll in suitable guide tracks 160 cut in an opposed frame plates 161 (FIGS. 21 and 26) each secured to an opposite fixed side frame structure of the machine. By means of suitable plate members 162, secured upon the end plates 22, 22' of the rotatable turret, guide tracks 160 include in each said plate an extension 160' to encompass the pivotal support of the web spindles 24, 24' with the track being continuous when said turret is in the cutoff position, as indicated in FIG. 1.

45 The first transverse bar 158 carries a cutoff knife 163 having a saw-tooth edge as best seen in FIG. 28. Each of said bars include bolted thereto a series of blocks 164 having a perforation therein and also a slotted recess 166. Within each of the perforations is inserted a compression spring 167. Thereafter springs 167 are locked in by means of a rod 168 inserted within the longitudinal slot 166. Upon each rod 168 is mounted twenty pressure rollers 169, there being a roller 169 and related compression spring 167 corresponding to each strip to which the incoming web may be slit. The rearward bar 158 has fast thereon a series of twenty tempered fingers 170 extending forwardly beneath rods 168 and which pass through suitable slotted openings in guide plates 171 fast to the respective bars 158. Said fingers serve not only to hold rods 168 in the respective slots 166 but also serve to guide the ends of the web ribbons following a cutoff operation, as hereinafter more fully to be described.

55 As shown in FIGS. 21 and 27, fastened to the rearward links of the roller chain 159 is a transverse frame member 172 having link connection 173 (see also FIG. 1) with corresponding left and right side operating arms 174. Said arms are fast upon the rock shaft 87 operable by arm 86 (FIG. 2) through means of the enveloper cam member 82. It will be recalled that the enveloper cam 60 comprises two tracks 83, 84 respectively and is rotated in exact synchronism with the web by means of the differential devices earlier described. Arm 86 with roller 85 thereon is biased inwardly by means of a spring tensioned arm 175 (FIG. 1) fast with shaft 87, so that said roller 75 normally rides the concentric track 83. Connected to arm

175 is an air cylinder motor C1 adapted upon operation, as in the manner hereinafter to be described, to impart counterclockwise bias to arm 175 and shaft 87, as viewed in FIG. 2, so that, roller 85 will follow track 84 and impart a positive reciprocatory movement to shaft 87. During the forward stroke of said movement arms 174 will advance the chain links 159, and the associated cut-off knife and enveloper means mounted thereon from the position of FIG. 21 through the successive positions around spindle shaft 24 as illustrated in FIGS. 23-25, and will thereafter be returned.

The enveloper cam 82 is designed to accelerate the enveloper parts up to the web velocity in the first portion of the stroke as the knife 163 approaches the web W, then hold at the web velocity during the period the knife contacts and severs the web, then to decelerate, reverse and retract to the starting position.

During the constant velocity and deceleration portions of the forward stroke the enveloper tracks 160, 160' guide the enveloper 158 around the empty spindle 24, which is rotating at web speed during this period. As the enveloper begins its envelopment of the spindle the knife 163 contacts the web W exactly at a selected cut-off point which is determined by control devices to be described hereinafter. Since the knife 163 and web W are both traveling at the same velocity, the knife point stays on the cutoff point. As the envelopment cycle progresses, the cutoff point on the web is caused to wrap around the knife edge while the knife pivots around rod 169, thereby building up web tension between said knife and the suitably placed guide roller 25 (FIG. 1). Toward the latter part of the constant velocity portion of the enveloper stroke, the knife points pull the web in direct line with roller 25; piercing through a selected line count of perforations of the web as will be described, and so independently of any other cutting means effect a severing of the web. In the meantime, the web having been gripped by the lead rollers 169 will be wrapped a partial turn around the empty spindle 24. These and the subsequent rollers 169 press the web against the winding spindle 24 with sufficient force so that said spindle takes over the function of pulling and winding the web even before the web is parted. Thus there is no interruption of web tension during the transfer of winding from the completed spindle 24' to the empty spindle 24.

Following the web severing operation, the enveloper begins the deceleration portion of the forward stroke. It may be noted that during this time the incoming ends of the severed ribbons which continue to move at uniform velocity will be caused to advance beyond the knife edge. However, it will be recalled that a series of tempered spring leafs or fingers 170 are secured for movement with the enveloper bars 158. As the enveloper devices above described are carried around the circular portion of track 160' (FIG. 21) the compression springs 167 acting on rods 168 and rollers 169 serve to cramp the spring leaves 170 in manner so that the forward ends of the leaves will be advanced forwardly of the edge of knife 163, as shown in FIG. 25. This forward advance of the spring fingers 170 acts to hold the ends of the web ribbons close to the spindle 24 and will direct them into a rolling nip between said spindle and the follower rollers 25 (FIGS. 1, 29 and 30) which ride on the web coils for controlling winding speed of the spindles, in the manner earlier described. A series of spring guide fingers 177 secured to the support arm 26 of the rollers 25 extend through suitable grooves in said rollers and serve to further guide the web ribbons into the nip between the oncoming web and the spindle 24. When the web ribbon ends enter this latter nip one complete wrap of the web around the spindle has been completed and the web is now secured thereto. At this point the enveloper cam track 84 (FIG. 2) acts to effect return stroke of the parts until returned to starting position,

where follower roller 85, the air cylinder motor C1 (FIG. 1) having been earlier released, will again follow the concentric track 83 of the enveloper cam plate 82.

Relative to the web cutoff operations, it is recalled in connection with the description of FIG. 11 that pin cylinder 12 is the control element of the servo system and the enveloper cam 82 is operated by shaft 81 in exact phase to follow the pin cylinder. Since the enveloper cam 82 is in exact phase with the pin cylinder and the pin cylinder is in exact phase with the perforated web, then the enveloper cam is also in exact phase with the perforated web. Each revolution of pin cylinder 12 and of enveloper cam 82 corresponds to twenty stamps of the web. Thus the enveloper cam 82 turns in exact synchronism with the perforated stamp web. The synchronism is with respect to the stamp perforations and not to length of web fed up so that synchronism with the stamp perforated cutoff point in the web is maintained.

The enveloper cam 82 is designed to give the enveloper a stroke with a constant velocity sector of the cam period during which the web is severed. The constant velocity sector of the cam being synchronized with the pin cylinder and with the stamp impression junctions by meshing the stamps with the pin cylinder at a suitable reference line on the cylinder. Then when the cutoff cycle of the enveloper occurs, the knife 163 will always contact the web at the stamp impression junction. As earlier described, to bring the reference line on the pin cylinder and the constant velocity cutoff sector of the cam 82 into synchronism, a manual rotation of adjustment wheel 110 (FIG. 11) will cause the enveloper cam 82 to rotate or move with respect to the pin cylinder 12 (or the pin cylinder to rotate with respect to the cam) so that exact phasing and cutoff control between the two can be accomplished.

As previously stated, the enveloper cam 82 is a face cam with two tracks, the inner track 83 (FIG. 2) being a simple circle and the outer track 84 designed to give the enveloper its motion. Initial operation of cam follower 85 it will be recalled is under control of an air cylinder motor C1 (FIG. 1) for pushing the follower 85 into the outer track 84. Air motor C1 is operated while the cam follower is on the inner segment of track 83 common to both tracks. As soon as follower 85 enters the outer track 84, air cylinder C1 is exhausted and cam 84 effects the drive for the enveloper stroke above described. On the return stroke, air cylinder C1 serves as an air cushioning means to decelerate the enveloper and cam follower mass and to work against spring means 175 (FIG. 1), thereby holding the cam follower 85 on the outer surface of the track 84 to provide a smooth, controlled deceleration, instead of dropping abruptly through the re-entrant space onto the inner track 83.

As hereinafter to be more fully described with reference to the control circuits for the machine, air motor C1 for timing and initiating the enveloper operation is controlled by a circuit switch S5 (FIG. 31A), operated by a single lobe cam member 178 fast to the shaft 81 of the enveloper cam. Fast also to shaft 81 is a second cam member 179 having two lobes which operate a circuit switch S4 twice during each revolution of said shaft. Switch S4 is in a primary circuit for pulsing upon each closing a counting means, such as the well-known Veeder Root counter, and with switch S5 comprise the heart of the control system for the coiler.

The stamp press means to which the coiler in the instant case is applied effects two impressions of ten stamps each impression, corresponding to the twenty stamps that pass the pin cylinder 12 per revolution of shaft 81. The two contact cycles of switch S4 correspond to the two said print impressions, or more exactly the number of stamp impressions as they pass the pin cylinder.

It is recalled that the solid web of stamps after passing through the pin cylinder 12 (FIG. 1) is fed between a

score cylinder 17 and a bank of slitter knives 16 for dividing the web into ribbons of any selected number of stamps in width. As shown in FIGS. 2 and 12, said cylinder 17 is driven (through a special slip clutch means 188 similar to that as hereinafter to be described with reference to operation of drag roller 9) by a drive chain 15 connecting a 26T gear 189, fast to the slitter support shaft 190, with the output shaft 59 of the first differential means, described with reference to FIG. 11. The purpose of driving the slitter cylinder 17 is to compensate for the drag produced by the friction of the slitter knives 16. Since the number of slitter knives may vary according to the number of stamp ribbons desired and to give the slitter mandrel extra torque on start up, suitable adjustable air pressure valves V17-V20 (FIG. 31A) to the slitter mandrel clutch 188 are provided, as shown diagrammatically in FIG. 31 and operable in a manner hereinafter to be described. Valve V18 controls the air to the slitter manifold. When it is "ON," the slitter knives 16 are against the mandrel or score cylinder 17 and when in the "OFF" position, the knives are retracted. Valve V17 is adjustable to compensate for any drag produced by the slitter knives 16. Valve V19 is a flow control valve to prevent any sudden build-up of air pressure in the manifold. This flow valve allows the slitter knives 16 to move into the score cylinder 17 slowly so that neither the knives or said cylinder will be chipped by the knives striking the cylinder at high speed.

It will be remembered relative to the webbing up operation described in connection with FIG. 1, that from the slitter means 16, 17 the slit web ribbons pass around certain guides rollers 18, 20 and 21 before reaching winding spindle 24. The guide roller 21 is equipped with removable spacing collars and guide discs 21 which may be stacked alternately thereon to provide for proper guide spacing according to the widths of the stamp ribbon pattern being coiled. To insure that one of said guide discs will always be in the center of the web, the shaft 21 is stepped to a larger diameter at the exact center thereof and two sets of discs and spacers are made with each set having the corresponding size for mounting on the related half of guide shaft 21.

Where web ribbons are restricted between discs type guide members such as above set forth, the face of the guide disc if rotating in the same direction as the web movement has the tendency to cause the web to climb free of said guides. In order to counteract such tendency, shaft 21 supporting disc 21' is driven in a reverse direction to the movement of web W, by suitable drive chain means 50, 51 in the power train, as shown in FIG. 3.

By rotating guide shaft 21 counter to the web, added tension is also caused to be built up in the web at the spindle 24' so that a more uniform and tighter wind is obtained in winding the web thereon.

Ribbon spreading rollers (FIGS. 1, 2 and 6)

When coiling narrow ribbons, for example, twenty single width stamp ribbons, it is necessary to separate each ribbon strip in order to allow room for the separating guide discs as mounted upon shaft 21, above described.

To fan the ribbon strips outward without introducing edge stresses thereto spreading rollers 18 and 20 are provided to operate in selected related pairs according to the slitting pattern to be made. The lower roller 18 is convex, as shown in FIG. 6, and being bearinged in the machine framing just above the slitter means 16, 17 while upper roller 20 is concave and mounted fast for rotation with the shaft 81 (FIG. 2) of the enveloper cam plate 82. Convex roller 18 directs the ribbon outward at a slight angle while the concave roller 20 will act to return them parallel to the web direction.

The degree of separating function of the rollers 18, 20 is related to the number of ribbons to be coiled. For instance, when two, ten width stamp ribbons are being coiled the amount of separation required is negligible.

When coiling four, five stamp width ribbons somewhat more separating effect is required and so forth up to the maximum separating effect needed for twenty, one stamp width ribbons, which of course requires the maximum number of guide discs on the shaft 21.

The following table of graduated curvatures therefore is recommended for the different slitting patterns that may be encountered.

Slitting pattern	Lower roller 18	Upper roller 20
Two 10 wide ribbons	Straight	Straight
Four 5 wide ribbons	Concave	Do
Ten 2 wide ribbons	do	#1 Convex
1 wide and 2 wide combinations	do	#2 Convex
Twenty 1 wide ribbons	do	Do
Three 5 wide and five 1 wide combinations	do	#1 Convex

Ribbon tension equalizers (FIGS. 1, 6 and 10)

To equalize the tension among the ribbons after slitting and to prevent the whole of the web tension from localizing in a few ribbons, which could cause ribbon breaks, the following means are provided.

Pivottally mounted upon a transverse rod 220 are twenty-one tension equalizing shoes 19, one for each of the twenty-one stamp ribbons or combinations thereof to which the machine is adapted. Shoes 19 are adapted under tension of respective springs 221 for engaging the gum side of the web on the span thereof between the ribbon spreading rollers 18, 20. The opposite end of springs 221 in groups of five are connected to a corresponding one of four related frame members 222 loosely supported upon transverse shaft 223. Each frame member 222 is individually adjustable by means of a related thumb wheel 224 whereby tension of the corresponding group of each five springs is adjustable for varying tension on the corresponding web groups.

A lateral arm 225 of each frame 222 is connected with a common cross bar 226 engaging a suitable gage means 227 for indicating the tension value equivalent to the total web tension.

By manipulation of thumb wheel 224, the operator is able to adjust the length of each group of ribbons to compensate for any irregularities and so obtain a uniform cutoff point across the web. As spring tension on a group of shoes 19 is increased, the cutoff point of the ribbons controlled by said shoes will move upstream.

Primary web tension drag slip clutch (FIGS. 1, 2, 7, 8, 12 and 31)

It is desirable during movement of the web through the coiler to maintain a given uniform tension upon the web and special drag means are therefore provided, as will now be described.

From the web entering dancer 1 (FIG. 1) it will be recalled that web W thereafter passes around a drag roller 9, supported upon the shaft 191 operated by 54T sprocket 192 (FIGS. 2 and 12) as driven by chain 15. Said roller is provided with suitable friction surface means so that the web in being pulled through the coiler by the active winding spindle 24 or 24' will drive the roller 9 without slipping thereon. Supported upon shaft 191 for drag roller 9 is a novel slip clutch 188, similar to the clutch 188 of earlier references for operating the slitter cylinder 17 on shaft 190. With the exception that clutch 177 for the slitter 17 is operated at a faster speed to the clutch 188' for the drag roller 9, both clutches are identical and will now be described in more detail with reference to FIGS. 7 and 8 showing one of said clutches in relation to the slitter shaft 190.

Sprocket wheels 189 and 192, driven by chain 15 (FIG. 2), are mounted fast with a respective disc 193 (FIG. 7), the hub 194 of which is loosely mounted for rotation upon a reduced diameter portion 195 of the support shafts 190, 191 for the respective slip clutches 188, 188'. Disc 193 includes a plurality of laterally bent lugs

196 embracing corresponding apertures in a friction slip ring 197 made of suitable low friction material, such as "Rulon," and being supported by the inside surfaces of said lugs 196. Mounted upon a shouldered portion 198 of each of the respective shafts 190, 191 is a press plate 199 the hub 200 of which is keyed by a wedge 201 for rotation with said shafts. Slidably mounted upon hub 200 and keyed for rotation therewith by spline means 202 is a back plate 203 upon the hub 204 of which is mounted a ball bearing support cage 205. A set screw 206 in plate 203 engages the left side wall of the inner race of said cage. The outer race of said cage supports an air piston 207 having a set screw 208 therein engaging the right end wall of said outer race. Piston 207 is slideable within the walls of a suitable air reservoir 209 formed within a fixed cylinder 210 and in which air is pumped by means of a connecting tube 211 extending to related air valves V17-V20 (FIG. 31), controlled in manner to be hereinafter described. Suitable gasket rings 213 are provided, so that, air entering reservoir 209 will act to displace piston 207 leftwardly (FIG. 7) causing set screw 208 therein to move ball cage 205 therewith and thus the lower race of cage 205 acting on set screw 206 will displace back plate 203, into functional engagement with the rotating slip ring 197. Thus, slip ring 197 now acts to drive both plate 199 and plate 203 which together rotate hub 200 and thus shaft 190 or 191 of the corresponding clutches 188, 188' related respectively to the slitter devices 17 and drag roll means 9, as earlier described.

Slip ring 197 on each friction face includes a series of grooves 215 extending from the outer peripheral edge to the inner edge formed by the central orifice 216 in said ring. Said grooves are arranged angularly in the direction of rotation as shown in FIG. 8 and are provided for the purpose of drawing along the friction face surfaces of the clutch any residue oil drops which form as lubrication is sprayed upon the clutch devices in the usual manner. The arrangement being such that the camming action of the grooves 215 will act to overcome the centrifugal forces tending outward distribution of the formed oil drops along said grooves. Oil upon exiting from grooves 215 is now dispersed along channels formed by a ring of small orifices 217 in the respective plates 199, 203 and acting to assure more efficient lubrication to the ball bearing means 205. It is intended that the clutches above described operate as constant slip clutches, and it will be noted that any oil passing along grooves 215 serves not only as a means for lubricating contact surfaces of slip ring 197 and the plates 199, 203 forced against said ring but serves to reduce frictional temperatures induced by slippage between said parts.

It is recalled that web tension slip clutch 188' is operated by chain means 15 (FIGS. 2 and 12), driven by the general coiler drive so that slip ring 197 rotates slower than the speed of hub 200 with shaft 191 and drag roller 9 as operated by the web W. It will be noted that in the present arrangement the hub 200 of the slip clutch is now the driven part rather than a fixed part as in the heretofore known drag clutch devices. Since hub 200 is driven at a faster speed than the speed of input by chain drive 15, it is obvious that relative motion between the two will produce drag at the slip ring 197, thereby providing tension to the web W.

The novel arrangement and parts above described provides for clutch means in which heating in the clutch is reduced to approximately only 20 percent of that as would otherwise be produced by the earlier known slip clutch devices. This lower heating contributes materially to uniformity in the drag control. Another advantage accruing is that some 80 percent of the energy to produce the web tension is now recaptured and returned to the coiler drive system, with the result that the coiler requires less horsepower to drive it. The described arrangement provides a slip characteristic in the clutch

which is uniform and relatively free of any starting or "stick" friction, as well as having the "soft" drag necessary to produce relatively low web tensions in a reliable manner.

As earlier stated, slip clutch 188 for operating the web slitting mandrel 17 is identical with slip clutch 188' operating the web drag roller 9. The only distinction being that to overcome friction and cutting drag of the slitter, drive chains 15 through gear 189 operates shaft 190 for the slitter mandrel drive clutch 188 at web speed, which is greater than the speed at which gear 192 operates drag mandrel 9. The torque delivered to the mandrel 17 through the slip clutch 188 is adjusted to just balance the drag of any slitters being used. As well-known, however, starting or "stick" friction is greater than running or "slip" friction and to overcome the higher "stick" friction without affecting the web tension, certain pneumatic control circuits are arranged to give the clutch field a pulse of increased air pressure each time the coiler is started, as will be hereinafter described in connection with the electrical control system.

Web winding spindles (FIGS. 1, 3 and 13-16)

As described earlier in the specification with reference to FIG. 1, two winding spindles 24, 24' respectively are mounted upon a turret 22 which can be rotated to bring each spindle successively to three functional positions: (1) the starting position where the running web is cut and attached to the fresh spindle (2) the winding position where the major portion of the web is coiled upon the spindle and (3) the unloading position where the finished coil is removed from the spindle. The turret 22 being secured in each position by means of suitable notches 33 in the peripheral edge thereof engaging an air operated latch member 34, controlled in manner to be hereinafter described.

As shown in FIGS. 13 and 15, winding spindles 24, 24' each include two parts with flat matching tapered surfaces along their longitudinal lengths. The sides adjacent said tapered surface are each substantially flat surfaces, while the sides opposite the tapered surfaces are of convex configuration. When the two parts are placed in cooperating position relative to each other along the tapered surfaces said convex surfaces form the spindle as circular in shape and of a given normal diameter, which in the instant case is approximately one inch. One said tapered part forms the main or body section of the spindle which extends outwardly of the turret and is supported by ball bearing means 230 mounted within the forward and rearward plates 22, 22' comprising the turret. Said body section has fast to one end thereof the gear 133 driven by the ball cage integrator devices earlier described with reference to FIG. 14. The second tapered section of the spindle is slideable longitudinally along the tapered surface of the body section. Both said sections are rotated as a unit by means of the projections 231 thereon engaging corresponding slots 232 of the respective sections. Suitable set pins when inserted in holes 233 to extend through related slots 234 in projections 231 will serve to lock the two halves of the spindle together.

Extending within the drilled shank portion 229 of the body section is a plunger 134 provided with a slotted end 235 for receiving a projection 236 of the slideable section of the spindle. Said plunger having suitable pin and open end slot engagement at 237 with projection 236. Nested within shank end 229 is a compression spring 239 which biases plunger 134 and thereby the slideable section of the spindle inwardly, or toward the left as viewed in FIG. 13. Thus, in normal winding condition the left end of the slideable section will be held against a shoulder 240 of the body section.

Encompassing each of the spindles 24, 24' is a metal shroud 241 made of spring tempered material, such as beryllium copper, and which is biased to conform with

the circular configuration of the spindles 24, 24'. To assure rotation with the spindle, shroud 241 includes a split seam along the full length thereof and one edge of the seam is bent inwardly to form a tongue 242 engaging a cooperating longitudinal groove 243 cut along the length of the body section of the spindle.

Pivotedly mounted upon a stud 244 (FIGS. 3 and 13), secured within frame 126 on the turret plate 22', is a bell crank lever 245, one end of which engages the end face of plunger 134. On the other end of bell crank 245 is mounted a roller 246 adapted in the indexing rotation of the turret to the unloading position to engage the lateral cam face 247 of a plate 248, secured to the main framing of the machine, and thereby impart a clockwise movement, as viewed in FIG. 13, to said bell crank. Upon clockwise movement of bell crank 245, plunger 134 is displaced rightwardly, forcing the slidable section of the spindle to move rightwardly therewith and along the tapered surface indicated by the line 249. During said movement, the fully webbed spindle 24' is caused thereby to collapse to a reduced diameter and shroud 241 also collapsing therewith releases its frictional hold of the coiled web, so that the web may now be easily removed by the operator.

Following removal of the web coil, the operator depresses a suitable control button S28 (FIG. 31) in the circuit means for indexing the turret 22, thereby bringing the now empty spindle 24' to the cut-off position and the active spindle 24, upon which the web is now being coiled, to the winding position. During this operation, roller 246 moves free of cam face 247 and compression spring 239 will restore the spindle 24' and associated parts to their leftward normal condition. A suitable set screw 238 in the outer end of the spindle serves by engaging tongue 242 to prevent a displacement of shroud 241 during said removing of a web coil from the spindle. For better friction with the web, shroud 241 is covered with a synthetic rubber material, such as the synthetic well-known to the art as "Viton." Also, to increase the gripping properties thereof in the circumferential direction while at the same time decreasing such property in the axial direction, said covering herein is scored along the surface thereof with close circumferential grooves.

Electric and pneumatic circuits (FIGS. 1, 31, 31A and 31B)

The electric and pneumatic control components are contained in suitable control boxes fastened at various locations of the main machine framing. There is both A.C. and D.C. power supply to operate the coiler control circuits.

As shown in the schematic diagram FIG. 31, A.C. power is supplied through an isolating transformer T1 which is 1:1 ratio and has connection by means of leads 250, 251 to the primary input source.

The insertion of this transformer allows one side of the A.C. control circuits to be grounded without introducing a hazardous situation. The D.C. power is supplied by a rectifier D1 and regulated transformer T2 also connected to leads 250, 251. A relay operated switch S17 in lead 250 controls the primary A.C. power to the machine in accordance with operation of respective push button switches S14 for starting and S23 for emergency stops.

It may be pointed out at this time that the master circuit includes two common ground systems for the various control circuits. One ground system is termed the primary reset ground system and being identified on the drawing by heavy solid lines 252, while the other is termed the secondary reset ground system and identified thereon by means of a dual solid and dashed line 253. The secondary reset ground system is caused to be broken upon the opening of a microswitch S8 (FIGS. 1 and 31) in the operation of arm 175 at the time the enveloper makes its forward stroke for a web cut-off operation. The primary reset ground system at the same time is caused to be broken

by virtue of a relay K-11 which also is controlled by switch S8 in engaging a contact member 254 for the purpose of turret indexing operations as hereinafter described. It is noted that primary ground 252 on terminal 8 of said relay K-11 serves also as ground connection for the secondary ground system 253, through first the primary lead 252, then in series a switch S7 closed only when turret latch 34 is in the latching position, a switch S2 closed only when the turret is in position for the start of a new coil and finally the said enveloper cam switch S8. At appropriate times the various control circuits are caused to be reset by being disconnected from said ground systems, as hereinafter to be described. For the present, it will be sufficient to say that disconnecting of the secondary ground system 253 by operation of the enveloper cam switch S8 in the forward stroke of arm 175 above described resets certain enveloper cut-off timing circuit relays K-6, K-7, K-8, and K-9. (FIG. 31A), as well as related cut-off controlling relays K-4 and K-24 (FIG. 31B), hereinafter more fully described. Also, operation of micro-switch S8 serves to restore a valve V-1 (FIG. 31B) to remove air from the enveloper air cylinder C-1 (see also (FIG. 1).

Before describing the circuit means in detail, it is believed that a brief description of the following controls and their purpose set forth in a general manner may be helpful in more easily understanding the control circuits.

(a) When 110 v. A.C. power is connected to the machine, a white lamp L6 (FIG. 31A) will light up.

(b) When the start button S14 is pressed, a green light L1 will light until the emergency stop button S23 is pressed. Start button S14 controls the electric power to the whole coiler. When pressed, power is connected through main switch S17 to the electric control circuits, which starts the web guide vacuum pump motor M and opens the main air valve V-13.

(c) Emergency stop button S23 when pressed, removes all electric and pneumatic power from the coiler. Thereupon the main switch S17 will open, also the vacuum pump motor M serving the system is stopped, the main air valve V13 is cut off and the pneumatic system exhausted.

(d) A manual cut-off button S6 is used whenever it is desired to cut off the web at any time and start a new coil. It controls the start of the enveloper cut-off sequence in proper synchronization with the web. If the web is synchronized on the pin cylinder, the cut-off will be at the impression junction of the stamp. When the web is cut off by this button, the "Veeder" counter S1 is reset to zero and a new count begins. A lamp L-7 in the cut-off timing circuit will light just prior to a cut-off cycle to indicate that the cut-off cycle has started.

(e) Thousands Selector and Hundreds Selector Switches S22 (FIG. 31B) and S21 (FIG. 31) are manually preset for determining the total stamps to be wound per coil. These switches together with the "Veeder" counter S1 control cut-off of the web and the start of a new coil when the required number of stamps have been wound on a coil. The two decade switches are set according to the number of stamps required on a coil. The thousands switch may be set to any number from zero to seven and the hundreds switch from zero to nine for a maximum count to 7900 stamps. With these two switches the coiler can be set up to wind coils in any size increments of 100 stamps.

(f) Jog Drive Button S13 (FIG. 31B) when depressed puts the coiler under the control of "forward" or "reverse" jogging buttons S16 and S15. A lamp L3 lights up when button S13 is pressed to indicate that the coiler is disconnected from the press drive and may be jogged by the correction motor 40. When on jog drive the clutch 36 (FIGS. 11 and 31B) connecting the coiler to the press is disengaged and the brake 36' on the coiler input shaft 35 is applied. The coiler can now be driven forward by pressing button S16, or reversed at will by pressing button S15. Said buttons control the correction motor 40 when the coiler is off press drive. The forward jog button is

interlocked with the dancer roller position so that when the coiler is webbed up, the web slack at the dancer roller cannot be completely wound up. This prevents web breakage at the coiler infeed as by inadvertent coiling up of the slack to the point where it is all used up and the web breaks. When the coiler is in jog drive, the press may be operated without affecting any operations of the coiler.

(g) Press Drive Button S12 when pressed, transfers the coiler from jogging motor control to the press drive. Its operation causes the brake 36' on the input shaft 35 to be released and the clutch 36 to couple the coiler to the press. When the coiler is coupled to the press, the dancer 1 acts to control the correction motor 40 to keep the press and coiler in synchronism by means of micro-switches S10, S11 at the up limit and down limit for the dancer. A light L2 in the circuit provides visible indication that the coiler is coupled to the press.

(h) Count Checking Switch S19 (FIG. 31A) is a double pole switch manually settable to three positions for connecting internal circuits which compare or cross checks a suitable counter means on the press with the "Veeder" counter S1 of the coiler. Checking is performed when switch S19 is in the clockwise or "run" position. The control circuits are so arranged that if one or the other counter is out of step at the time the web coil is cut off, a lamp L5 (FIG. 31B) will light to indicate an error in the count. The light may be extinguished and its circuit restored to normal by pressing a reset button S18A near the count error lamp L5.

With the counter checking switch S19 (FIG. 31A) in the "run" position, a cut-off signal will come from the "Veeder" counter S1 of the coiler. To bring the press counter means and the coiler into synchronism at the web up or start of a first roll of stamps the count checking switch includes a "start" position. In this position, the press counter and the coiler counter are both connected into the cut-off initiating circuit. The signal from the press can now be used to cut off the stamp roll and to start the count with both counters counting together. Once the coil is started, the count checking switch may remain in any of the indicated three positions.

Start.—If left in the "start" position, both counters will be connected to the cut-off circuits. If now there is an error in counting, i.e., if one counter gets out of step, the first counter to reach the selected final count gives the cut-off signal.

Off.—If left in the "off" position, the counter S1 on the coiler serves to control the cut-off, with no count checking effected.

Run.—In this position, the counter S1 on the coiler will control the cut-off and will be checked against the press counter. If the two counters get out of step, the count error signal is given.

(i) Pre-signal cut-off selector switch S9 (FIG. 31B). This switch is manually pressed to select the time at which the control circuits for safety reasons will check the position of the turret in anticipation of the web cut-off. There are two signal settings of switch S9, one for 10 impression (100 stamps) and one for 20 impressions (200 stamps). Thus either ten or twenty impressions (100 or 200 stamps) before cut-off a pulse signal will be generated which will check whether or not the turret is in the right position for a cut-off. It is in the right position only if it has made a complete 180° of rotation from the previous cut-off position. If the turret has not moved from the previous cut-off position or is in the unloading position, or is in motion the checking signal will report that the turret is not in the position for a cut-off cycle. This will cause the coiler to be stopped by transferring from the press drive to the jog drive and the turret safety lamp L4 will light up to signal the operator to make any appropriate corrective operations.

Turret Index Button S28 (FIG. 31) is a manual switch used to index the turret from the unloading position to the cut-off position. The circuit will only operate when the turret is in the unloading position.

Under the automatic control of counter S1, the turret indexing from the winding to the unloading position will start on the fourth impression after a cut-off operation, so that, three and a fraction impressions of stamp web are wound on the spindle while it is in the enveloper position. The reason for winding this amount before indexing the turret is to allow the tail of any finished coil to be completely wound on the coil before the spindle stops turning at the unloading position.

Two restraining brushes 217 (FIG. 1) are provided to hold and guide the tail ends of the ribbons until they are completely wound on the coil. The brushes are automatically brought into position by the control circuits and are released after the turret reaches the unloading position as hereinafter described.

As earlier stated, the heart of the control system for the coiler is the timing pulses produced by the electric cam switches S4 and S5 located on the enveloper cam shaft 81 (FIGS. 1-31A). The pulses produced by these cam switches actuate the counter circuits and time the operation of the enveloper mechanism. The switch S4 it is recalled is operated by a two lobe cam 179 on the enveloper shaft 81 and makes two pulse contacts for each revolution of said shaft. These contact pulses correspond to the two print impressions of the press as timed per each revolution that the cam shaft makes and therefore switch S5 is timed to operate cut-off control relay K-5 so that any random cut-off signals that may be received from the press triggering source or from the manual cut-off button S6 are always completed at a common given time in the cycle of the enveloper cam shaft 81.

Operation of the counting circuits

As above set forth, the Veeder Root counter S1 (FIG. 31A) is operated through relay K-23, which in turn is operated by the cam switch S4. Two counts per revolution of the enveloper cam shaft 81 are recorded and each count represents ten stamps. Therefore, a complete revolution of the enveloper cam occurs with each twenty stamps of web wound on the spindles. Since the enveloper cam controls the cut-off of the web, any coils that are wound on the spindles can have a length that is any reasonable multiple of twenty stamps. As a practical matter, however, the control circuits and coil length selection switches herein are arranged to provide coils in any multiples of one hundred stamps in length.

Upon each pulsing of relay K-23 by the counting control switch S4, a pair of contacts 9, 11 of said relay will close and extend ground circuit by way of normally closed contacts 5, 6 of a relay K24 (FIG. 31B) and lead line 255, the closed contacts 9, 11, and a lead 256, including the condenser C8 and resistor R9, to the count solenoid R11 for imparting a count movement to the Veeder Root counter S1. The count solenoid R11 pulls up on the charging current to condenser C8, then releases as the charging current returns to zero. The two solenoid motions complete the movement for a one unit count in the counter S1. To be certain that condenser C8 is completely discharged and that the two solenoid strokes are accomplished, a contact 8 of relay K23 engages contact 11 thereof when said relay releases for the next cycle and will short circuit condenser C8. Each time contacts 9, 11 of K23 close one count representing ten stamps is thus registered on counter S1.

The counter S1 includes three decade readout tap switches, identified as the tens, hundreds and thousands switches and each fast to the corresponding decade numeral wheel of the counter. The wiper 257 of the tens decade readout switch advances one unit for each count effected by the closing of relay K23. The wiper 258 of the hundreds decade advances one unit each time the tens decade changes from nine to zero. The thousands decade wiper 265 also one unit when the hundreds decades changes from nine to zero. Upon reset all decades 75 return to the zero position.

The controls of the coiling machine are arranged so that the web cut-off cycle is initiated or started one count, or ten stamps, before the cut-off point on the web is reached. That is, if coils 500 stamps in length are being made the cut-off will be triggered by the counter on the 49th count, which corresponds to the 490th stamp. For 1000 stamp coils cut-off, triggering will occur on the 99th count, or 990th stamp. For a 5000 stamp coil, the trigger circuit occurs on the 499th count, and so forth.

The wiper 257 of the tens decade readout switch is connected to ground over lead 259 and the normally closed contacts 1, 4 of relay K23. Said contacts being opened when K23 is energized so that the circuit is disconnected to wiper arm 257 as the counter is being advanced. This arrangement not only prevents the rather fragile wipers from making and breaking current but also provides for accurate timing of the functions controlled thereby.

During the counting operation, two preliminary cut-off signals will be generated. A first signal, as hereinafter more fully described, is generated at 100 counts on the counter S1, which corresponds to 1000 stamps before a cut-off and will act in manner to be described to close a relay K1 (FIG. 31B). Operation of relay K1 closes a pair of contacts 6, 7 thereof which serves to extend a circuit from the pre-signal cut-off selector control switch S9 through lead 261 to a relay K-2 in the cut-off control train. At the same time, a pair of contacts 9, 11 of relay K1, when closed, extends a control circuit from lead 262 in deck "4" of the hundreds selector control box S21 and over leads 263, 263' to the relay K24, which includes a pair of normally closed contacts 1, 4 thereof in the circuit. Said relay being the final link in a chain of control for the cut-off operations, as will be described. Thus, in energizing relay K1 the said first or thousand stamp pre-cut off signal serves principally by said extension of the above control circuits to transfer control of the cut-off to the hundreds selector S21 for the hundreds stamp decade of the counter S1.

The second pre-cut off signal is effected from said hundreds stamp decade, as in the manner hereinafter described, and is timed to occur at either 100 or at 200 stamps from the cut-off line according to the manual setting of the pre-signal cut-off selector switch S9. Through closed contacts 6, 7 of relay K1 and lead 261 earlier described, said signal serves to close relay K2 for one-half of a counting cycle. Operation of relay K2, by closing a pair of contacts 9, 11 thereof, will extend primary ground circuit 252 over a lead 266 to close a relay K3 which, as hereinafter described, sets up a final control in the cut-off circuitry. Relay K3 at this time remains energized by virtue of a holding circuit extending thereto from primary ground 252, through closed contacts 1, 3 of said relay and leads 308, 266.

The momentary closing of relay K2 above described also makes a check for determining whether the spindle turret is in correct position for a cut-off operation. This is done through means of the pairs of contacts 1, 3 and 6, 7 of said relay which are connected in series with a circuit lead 267 connecting a contact member 268 of the turret latch switch S7 with a contact member 269 of the switch S2 operated by suitable cams 270 (FIG. 1) on the turret 22. If latch pawl 34 is not seated within one of the holding notches 33 in the turret, a grounded arm 271 of switch S7 is held operated against contact 268 and thus will extend ground therefrom over lead 267, through contacts 6, 7 of K2 to a lead 272, thereby grounding and operating a safety relay K13 (FIG. 31B) which causes the coiler to be transferred from press drive to jog drive control, while bringing the machine to a stop. In like manner, if the turret is not in the cut-off position, no cam 270 will engage switch S2 and a grounded contact arm 273 thereof then engages contact 269 to extend ground therefrom by lead 267, through contacts 1, 3 of relay K2 to the

lead 272 for operating relay K13, whereby to stop the machine.

The sequence of operation of the counting and control circuits may more clearly be understood in connection with the following illustrative examples.

5 *Example 1.*—Assuming that 500 stamps are to be wound per each coil.

As shown in the wiring schematic (FIG. 31-B), the thousands selector switch S22 comprises three decks of ten contact pins numbered "0" to "9," with an associated contact wiper for each deck. Said wipers move as one and are normally settable by a common control knob for selective engagement with said pins. The hundreds selector switch S21 (FIG. 31) comprises five decks of contact pins "0" to "9" and related contact wipers which also move as one and are manually settable for selective engagement therewith.

Thus for 500 stamp coils the thousands switch S22 would be set at the "0" contact pins and the hundreds switch S21 would be set at the "5" contact pins. Of course all wipers of the "Veeder-Root" counter start from zero. With the thousands selector switch S22 in the zero position, ground from the primary circuit lead 252 is extended by wiper arm 291 from deck two thereof over a lead 274 to the number "5" contact pin in deck five of the hundreds selector switch S21. The wiper arm 287 of said switch being on the number "5" contact pin, ground is now extended therefrom to the coil of relay K1, over lead 275 and the normally closed contacts (1-4) of said relay. Relay K1 is thus caused to be operated and by means of a self-locking circuit, through contacts 1-3, thereof remains locked up throughout counting operations.

As counting proceeds, the readout wiper 257 of the tens order of the counter S1 will move through the "9" contact three times, thereby moving the hundreds readout wiper 258 up to engage the related "3" contact pin. Said pin has connection over lead 276 to the number "5" contact pin in deck number "2" of the hundreds selector switch S21 and, since the wiper arms of said switch in the present example are set for five hundred stamps, circuit from deck "2" is extended by means of lead 277 to the center pin 278 of the "Pre-Signal Cut-Off Selector" switch S9. Contact arm 279 of said switch in the instant example is preset by the operator to the one hundred contact pin 278, so that the second of the above described two pre-cut off signals is determined to occur one hundred stamps prior to actual cut-off. It is recalled that with the thousands selector S22 at "0" contact position the primary circuit from deck "2" thereof extends over lead 274, the "5" contact of the hundreds selector switch S21, lead 275 and normally closed contacts (1-4) for energizing relay K1. Contacts (6-7) of said relay thus being closed circuit from lead 260 of the switch S9 above described is extended over lead 261 to the relay K2. Therefore as the wiper 257 of the tens decade of the readout counter S1 next comes to rest on related contact pin "9" for a total count of thirty-nine (390 stamps and 100 stamps before the cut-off signal of 490) a pulse from contacts (1-4) of relay K23, is extended over lead 259, tens wiper 257 and contact pin "9" of the tens decade of counter S1, lead 218, the "hundreds" wiper 258 and related contact pin "3" thereof, lead 276, thence through pin "5" of deck 2 of the hundreds selector switch S21, the closed contacts 278, 279, of S9, lead 260, the closed contacts (6-7) of relay K1, above described, and lead 261 to thereby energize the control relay K2, whereby the circuit will thus be primed for the cut off control sequence earlier set forth with respect to said relay K2.

Upon the next count the "tens" readout wiper 257 moves from "nine" to "zero" and the hundreds decade wiper 258 moves up to engage the number "4" contact pin. Nine counts later the "tens" wiper 257 again engages the corresponding "9" contact pin and another pulse generated by relay K23 at this time however will now be extended from the active number "4" contact pin of the

"hundreds" decade and through a lead 280 to the number "5" contact pin of the first deck of the hundreds selector switch S21. Wiper arm 281 of said switch being on said contact pin the circuit pulse is extended over lead 282 to the wiper arm 265 of the "thousands" decade which remains set at normal condition in engagement with the related "0" contact pin, and by means of lead 283 to the "0" contact pin of deck 1 of the thousands selector switch S22. Said switch also remaining set at zero contact arm 284 thereof is in engagement with said contact pin and the circuit impulse is extended over a lead 285 to the number "5" contact pin in deck 4 of the hundreds selector switch S21. Wiper arm 286 of said switch being set at contact number "5" said pulse continues by way of lead 262, previously closed contacts (9-11) of relay K1, the leads 263, 263' and through contacts (1-4) of relay K24 to thus operate said relay K24. Relay K24 is the final link in the chain of control for a cut off operation and for resetting the counter S1, as in manner hereinafter to be described.

Example 2.—Assume the cut off selector switches are set up to determine coils of one thousand stamps per coil. Thousands selector switch S22 is manually set at "one" and hundreds selector switch S21 would be set at "zero." Ground from primary lead 252 is now applied to the coil of relay K1 from wiper arm 288 engaging the number "1" contact pin of deck three of S22, over lead 289 to the "0" contact pin in deck five of the hundreds selector S21 and wiper arm 287 now being in engagement therewith circuit is extended over lead 275 and contacts (1-4) to said relay K1, which operates as in manner described for the previous example.

The count now proceeds in the counter S1 until the hundreds decade wiper 258 reaches "7" and the tens decade wiper 257 is again on "9." This is a count of 79 (790 stamps) which is 200 stamps before the cut-off signal at 990 stamps for a 1000 stamp coil. If the pre-signal cut-off selection switch S9 in this instance has been placed on the contact pin 278' for a two hundred stamp pre-signal, then relay K2 will be connected over lead 260, 261 to operate as before and the circuits will be primed for the cut-off control sequence of earlier reference and as more fully described hereinafter.

As the counting proceeds, the hundreds wiper 258 of counter S1 reaches the "nine" position and the tens wiper reaches its "nine" position. The initiating pulse generated by relay K23 for the relay K24 in the present example goes over lead 218 to wiper 258 and thus reaches the coil of said relay K24 through the "nine" tap of the hundreds decade, lead 219, the "zero" tap and wiper 281 of deck L of S21, lead 282, the "zero" tap of the thousands decade, lead 283, the "one" tap and wiper 291 of deck 2 of S22, lead 274, the "zero" tap and wiper 286 of deck 4 of S21, lead 262, the closed contacts (9-11) of relay K1, and leads 263, 263' to energize relay K24 as before and the cut-off and counter reset cycles proceed.

Example 3.—Assume that the selector switches are set up for determining coiling 2500 stamps to a coil. The thousands switch S22 will be set at the "2" position, the hundred selector switch S21 will be set at "5" position and the wiper 279 for pre-cut-off signal selector S9 will be set at the "200" stamp pre-signal position. Relay K1 in this instance is not operated by the setting of S22, as for the earlier Examples 1 and 2.

Counting operations now will proceed without any cut-off circuit activity until the count of 149 (1490) stamps is reached. At this count the pulse from contacts (1-4) of relay K23 to the tens wiper arm 257 is conducted to the "nine" tap of the tens decade, lead 218, to the "hundreds" wiper 258, from the hundreds wiper to the "four" tap of the hundreds decade, lead 280, through the "5" tap and wiper 281 of deck 1 of the hundreds selector switch S21, lead 282 to the wiper arm 265 and number "one" tap of the thousands decade of counter S1, over lead 290 to tap "2" in deck two of the thousands selector switch S22, the

wiper arm 291, engagement therewith, lead 274 to tap "5" and wiper 287 in deck five of the hundreds selector switch S21, lead 275 and through the normally closed contacts (1-4) of relay K1 to the coil thereof for operating said relay. As heretofore described, relay K1 is held operated by a holding circuit from primary ground lead 252 through contacts 1-3 of said relay.

From this point counting proceeds to the count of 230 (2300 stamps) at which count relay K2 is closed momentarily as previously described, the pulse going to the contact 278' of the pre-signal cut-off selector S9 through the number "2" contact pin of the hundreds decade of the counter, lead 181 and tap "5" deck "3" of the hundreds selector switch, and by wiper 279, lead 260, contacts (6-7) of relay K1 and lead 261 to said relay K2. At the count 249 (2490 stamps) as this wiper 257 engages the number "9" contact the cut off control relay K24 is operated, over lead 218, wiper 258 engaging contact "4," lead 280, contact "5" deck "1" of the hundreds selector S21 lead 282, wiper 265 engaging contact "2" lead 339 to contact number "2" deck "1" of the thousands selector S22 and by wiper 284 thereof and contacts 9-11 of relay K1 as in the manner previously described.

The above complexity of tap switches and inter-connections to the counter decade are necessary because the counter cannot be reset to "one" but must reset to "zero" making it necessary to trigger the cut off at one less than the full count. The operation of resetting the counter to zero then occurs on the first count and in place of it. The circuit also gives the turret position test signal 200 stamps before cut off.

Counter resetting circuit

As earlier described, the counting coil R-11 (FIG. 31A) of the counter S1 is connected to ground through lead 256, contacts (9-11) operated by relay K23, lead 255 and the contacts (5-6) of relay K24. In operations of relay K-24 above described, contacts 5-6 thereof are caused to be disengaged and will interrupt ground circuit of lead 255 to the counting coil R-11 thus immobilizing said coil during the reset cycle of the counter. At the same time contacts (6-7) of said relay will close and connect ground therefrom to the reset coil R-12 of the counter S1 through means of lead 292, contacts (9-11) of cut off relay K5 which is timed to operate at the proper moment and the lead 293. So that a new count can begin as soon as the reset pulse has stopped, contact 11 of relay K5 re-engages related contact 8 thereof to immediately extend ground lead 292 over the lead 294 to the lead 255 and so back to the contacts (9-11) of the counter control relay K23. This prevents the loss of a count in the event that relay K24 should be slow in opening. The counter reset operation takes place during the time interval of one press impression for the stamps.

Enveloper control circuits

It will be recalled in connection with the description of the enveloper means with reference to FIGS. 1 and 2 that the enveloper stroke which causes the stamp web to be cut and started on a fresh spindle is controlled by the enveloper cams 83, 84 (FIG. 2). The enveloper stroke being initiated by the operation of an air cylinder C1 (FIG. 1).

As shown in the schematic (FIG. 31B) air cylinder C1 is controlled by an electric air valve V1, which in turn is controlled by a relay string including relays K24, K23 and K4 above described. The cut-off pulse, signaling the beginning of a cut-off cycle, may come from the counting circuit by means of contacts (9-11) of relay K1 as in the manner heretofore described, or may come from an external triggering circuit by means of contacts (9-11) of a relay K19 (FIG. 31) to be hereinafter described. It will be recalled that a cut-off pulse causes relay K24 to operate and to be held operated by the reset ground connection contacts (1-3) of said relay. Both of the cut-off pulses that actuate relay K24 are timed with respect to the rotation of the enveloper cam and will occur during the wind-

ing of an odd numbered impression indicated upon the counter S1. Upon operation of relay K24, the contacts (9-11) of said relay connect the secondary reset ground line 253 by lead 295 to the contact 7 operated by relay K23. Relay K23 however will always be in an unoperated condition at the time relay K24 closes. Upon a subsequent closing of relay K23 at the precise time the enveloper air cylinder C1 is to operate relay K4 is now caused to be operated over lead 295' and contacts 1-4 of said relay, through closure of contacts (6-7) of relay K23. The previously described operation of relay K3 having extended secondary ground lead 253 by closed contacts 9-11 of said relay and lead 309 to contacts 9-11 of relay K4 this results in the air cylinder C1 (FIGS. 1 and 31B) over lead 309' operating while roller 85 of arms 86 (FIG. 2) of the enveloper means is on the inside track 84 and just approaching the outside turnout of track 83 of the enveloper cam 82.

Cut-off timing

The purpose of the cut-off timing circuit is to provide that any randomly timed cut-off signal either from the press counter circuits or as initiated by the manual cut-off switch button S6 (FIG. 31A) will be timed to occur at the proper time in reference to the rotation of enveloper cam 82, as above described for the counting circuit. Thus any signal impulse is herein timed to begin with the closing of the enveloper timing switch S5 on the enveloper shaft 81 (FIG. 31A) regardless of the time or length of any random cut-off signal. Also the circuit is made incapable of receiving or generating another cut-off signal.

Cut-off relay K5 is cycled, over lead 296, in time with the enveloper cam shaft 81 through the timing switch S5. When relay K5 is operated the enveloper cycle, earlier described, is initiated. At this time certain relays K6, K7 and K8 associated with cut-off relay K5 are in their normally unoperated or released condition.

As earlier set forth in connection with the purposes of the "Count Checking" switch S19, when said switch is at "start," the web cut-off signal will be under single control of suitable counter means on the press, or by operation of manual cut-off switch S6.

At the desired appropriate time a signal impulse from the press counter will effect operation of a relay K27 to close contacts (1-3) thereof for extending the secondary ground lead 253 over lead 297 and energize the relay K9 in the cut-off timing circuit. Also, any operation of the manual cut-off switch S6 will act independently to extend ground from leads 253 and 257 to energize relay K9. With cut-off relay K5 in the unoperated condition as shown, operation of relay K9 will complete ground circuit from lead 253, through closed contacts (1-3) of relay K9, lead 298, closed contacts (5-6) of cut-off relay K5 and lead 299 to the coil of relay K6. Relay K6 will thus be operated and is locked up by means of its contacts (1-3) connected to ground lead 253. If cut-off relay K5 happens to be in operated condition when relay K9 or manual switch S6 is closed, then nothing would happen until relay K5 is released on the next open phase of the enveloper timing switch S5. By this circuit arrangement, K6 is caused to close at a consistent point in the cycle of enveloper cam 84 (FIG. 2) on shaft 81.

When relay K5 next closes, a circuit is completed through contacts (6-7) of said relay, lead 200, closed contacts (6-7) of energized relay K6, lead 301, normally closed contacts (1-4) of relay K8 and lead 302 to the count checking switch S19. The completion of this circuit is the start of a voltage pulse of a controlled duration which appears at the checking switch S19. If said switch is in the "start" position this pulse will be extended over lead 303 to energize relay K19, thereby causing an operation of the enveloper and the start of a new stamp coil on the upper spindle and simultaneously resets the counter to zero, as hereinafter described. If switch S19 is in the "run" position, this pulse alternately will be extended over lead 304 including normally closed contacts (1-4) of a

relay K16, to energize a relay K15 in the "miscount safety circuit" train, adapted to cross-check operations of the press counter with the operations of the coiling machine counter S1, in the manner to be described.

At the same time that the described voltage from contacts (1-4) of relay K8 is applied to count checking switch S19 said voltage is also applied by means of normally closed contacts (5-8) of said relay and lead 305 including a resistor R15 to cause an operation of relay K7, thereby closing the contacts (1-3) thereof. Closure of said contacts will apply common (ground lead 253) potential over lead 306 to the relay K8. However, the same potential has been previously applied to the other terminal of said relay K8 from lead 305 and since there is no potential difference across its coil relay K8 at this time does not operate.

The above described sequence and conditions prevail as long as relay K5 remains operated and its contacts (6-7) are closed. When relay K5, is subsequently released contacts (6-7) thereof will open, thereby interrupting the pulse to switch S19. At the same time ground is removed from the terminal numbered 7 of relay K8 but ground will still remain on the terminal 2 thereof whereupon relays K7 and K8 are now connected in series manner through resistor R15. Thus relay K8 will now operate while relay K7 remains in its operated condition earlier set forth. Operation of relay K8 opens the described pulse circuit to S19 so that upon a next and subsequent closures of relay K5 there will not be a repetition of the cut-off pulse at S19. Additional cut-off pulses therefore cannot be generated through this circuit until relays K6, K7, K8 and K9 are released. The reset timing circuit then remains quiescent with relays K6, K7 and K8 closed until the secondary reset ground lead 253 is interrupted in an operation of the switch S8 controlled from the enveloper cam shaft 81. Thereafter the reset timing circuit cannot again be operated until the spindle turret has made a full 180° rotation to place a fresh spindle in the cut-off enveloping position, when the switch S7 operated by the turret latch pawl 34 and the switch S2 at the turret winding position are both again closed, thereby restoring both the primary and secondary circuit leads 252, 253 earlier described.

Cut-off operation with count checking switch S-19 in "Start" position

The external cut-off triggering signals, as occurring from the press counter circuits to the control relay K27 or in an operation of the "Manual Cut-Off" button S6 will cause the cut-off cycle to operate only when the "Count Checking" switch S19 is in the "Start" position. When the count checking switch is in either the "Off" or the "Run" positions, the cut-off is controlled only by the counter S1 of the coiler. The purpose of this arrangement is to permit the coiler and press counter devices to be synchronized with the count checking switch S19 in the "Start" position.

An operator may thus select either a counter associated with the press or the counter S1 of the coiler to control a cut-off during coiling operations.

It will be recalled that with the count checking switch S19 in the "Start" position, a cut-off triggering pulse from the cut-off timing circuit lead 302 is extended over lead 303 to a relay member K19 (FIG. 31) which is closed thereby for the duration of the pulse. Upon said operation of relay K19, the contacts (6-7) thereof are closed to extend primary ground lead 252 over leads 307, 308 to energize relay K3, which relay is then locked up through the closure of the contacts (1-3) thereof. Operation of relay K3 also closes the contacts (6-7) thereof to partially complete a ground circuit from the secondary service lead 253 to the enveloper cylinder valve V1 by means of a lead 309 extending from said contacts to the open contacts (9-11) of the cut-off control relay K4. During the above operation of the relay K19, a pair of contacts 9-11 associated therewith are also closed to extend ground circuit 252, over leads 264 and 263', through

closed contacts (1-4) of the control relay K24 and thereby energize said relay K24, which is immediately locked up through its contacts (1-3). The condenser C5B across the coil thereof serving to resonate the coil at the 60 cycle power frequency and because of a transient current condition generated causes the coil to hold the relay during the transfer of the holding circuit to terminal 3. Relay K24 being closed, a cut-off cycle proceeds as in the manner earlier described for said relay.

Cut-off circuits with count checking switch S19 on "Off" or on "Run" position

With switch S19 on either "Off" or on "Run" position, the counter S1 controls the timing of the cut-off operation by producing the following sequence of relay operations. It is recalled that when any count reaches a point that is one thousand stamps less than the desired final count, a control circuit from the thousands selector S-22 will act, as in the manner heretofore described, to operate the one thousands pre-signal relay K1. Operation of relay K1 through its contacts (9-11) thereupon completes a control circuit over leads 263, 263' to energize relay K-24. At the same time contacts (6-7) of relay K1 are closed connecting the pre-signal cut-off selector switch S9, earlier described, over lead 260, said contacts (6-7) and the lead 261 to the relay K2. Relay K1 will be held in operated condition through means of the now closed contacts (1-3) operated thereby.

As earlier described, when the count reaches either 200 or 100 stamps less than the final count, according to the setting of the pre-cut-off selector switch S9, a pulse is delivered to the coil of relay K2 which closes only for the duration of the pulse. The momentary closing of relay K2 accomplishes two purposes. First it makes a check in the manner hereinafter described to determine that the turret 22 and associated latches 34 therefor are in the correct position for a cut-off cycle and second through contacts (9-11) of said relay K2 to operate relay K3 over lead 266, as earlier described. It will be recalled that operation of relay K3 through contacts (6-7) thereof and lead 309 closes a preliminary circuit to the valve V1 for the enveloper cam follower cylinder C1, see also FIG. 1.

Now, when the count reaches one less than the final count a pulse is delivered from the counter S1, through the proper selecting tap switches of the thousands selector S22 and hundreds selector S21 and so through contacts (9-11) of relay K1 to the coil of relay K24 to initiate the cut-off cycle, all as in manner heretofore described.

Count checking circuits

The count checking circuit compares the timing of the cut-off pulse received from the press counter to relay K27, described earlier, with that of the cut-off signal generated by the internal counter circuits of the counter S1, checking being based on the sequence of the two pulses.

When the count checking switch S19 is set in the "run" position, the cut-off is always controlled by the internal circuits of the coiler counters, as in manner earlier described. Even though cut-off signal pulses are continued to be received from the press, they do not now control a cut-off. Instead, they are carried via switch S19 and lead 304 to the relay K15 of the count checking circuit. The internal cut-off control signals from the relays K23, K24 extend by means of lead 311 from lead 295' associated with said relays to the count checking switch S19 and then by means of lead 312 to the relay K16.

For correct timing between the external and internal cut-off signals, the internally generated cut-off signal from the coiler counter S1 must begin sometime between the beginning and ending of the externally triggered pulse from the cut-off timing circuits. If the signal begins either before or after the pulse, the count checking alarm circuits are adapted to operate and signal a count error. The purpose of relays K15 and K16 is to monitor the sequence of the signal pulses and to control a relay K14 for holding

active an alarm indicating lamp L5, as in the following manner.

In normal operations a pulse from the cut-off timing circuit lead 302 to the count checking switch S-19 occurs first in time and is applied to the coil of relay K15 through the normally closed contacts (1-4) of the relay K16. Relay K15 is held operated throughout the duration of this pulse. While relay K15 is thus operated, the cut-off signal pulse from the internal counter S1 energizes relay K-24 whereby ground from closed contacts 9-11 thereof to lead 295' arrives over lead 211 to switch S19 and lead 312 to energize relay K16. Upon operation of relay K16, the contact arm 1 thereof is displaced from the corresponding contact 4 to the contact 3 of said relay, thereby extending a ground circuit from the closed contacts (1-3) of the previously operated relay K15 to effect a holding circuit over leads 313, 313' on said relay K15. Operation of relay K15 opens related contacts (5-6) thereof included in a circuit line 338 through contacts (6-7) of relay K16 to the alarm relay K14 and lamp L5, so that, while relay K15 is operated, an operation of relay K16 above described cannot operate said relay K14 and lamp L5. If the internal cut-off signal from counter S1 occurs before the external cut-off timing pulse begins or after it ends, which would indicate that the press and coiler were out of time, relay K16 would close first thereby closing the circuit to the error alarm relay K14 and lamp L5. A holding circuit through lead 314 (FIG. 31B) including contacts (1-3) of relay K14 will hold said relay and lamp L5 active until a release key S18A in the circuit is depressed. In connection with the above, it will be noted that lead line 338 will be connected to ground through an operated pair of contacts (6B-7B) of relay K17A to be hereinafter described.

Turret indexing control circuits

When the enveloper cam follower switch S8 (FIG. 31) operates as the cam follower 85 (FIG. 2) follows the outer track 84 of the cam plate 82, secondary ground lead 253 is connected to contact 254 and over lead 315 to energize the turret indexing control relay K11, which thereupon closes the contacts (6-7) and (1-3), while opening the contacts (8-11) associated therewith. Contacts (6-7) are thus connected to ground over lead 316 and switch arm 273 to provide a holding circuit for relay K11. Opening of contacts (8-11) serves to disconnect the primary reset ground line 252 and thus also secondary reset ground lead 253 and all cut-off timing circuits are thereby restored to their normal or unoperated condition.

Normally open contacts (1-3) of relay K11 has connection by means of lead 317 to the number (4) contact pin in the tens order readout of the counter S1 and is connected also by means of lead 318, including normally closed contact arm 319, to the coil of relay K12. Thus upon the 4th count made by the counter S1 after the cut-off cycle, ground is caused to be connected for energizing said relay, through contacts 1-3 of relay K11 as wiper arm 257 engages the said number (4) contact associated therewith. Relay K12 thus closes and is locked up through wiper arm 319, which disconnects from lead 318 and engages opposed contact member 320 in lead 320' connected to ground lead 316. Operation of relay K12 also closes the contacts (6-7) thereof connecting ground lead 320' to lead 321 extending circuit to the turret locking pawl cylinder valve V4, which thereupon lifts the pawl 34 out of latching condition with the turret 22. Upon said lifting of pawl 23, the switch S7 is caused to engage the circuit arm 271 thereof with contact 268, thereby over leads 267, 322, energizing the turret indexing motor valve 70 V-9, which causes the turret to rotate. As the turret rotates off of the winding position indicated in FIG. 1, the cam block 270 releases switch S2 which thereupon operates to open the holding circuits described for relays K11 and K12 and thereby restores said relays to normal. Thus while the turret rotates a fresh spindle to the enveloping

position, the secondary reset ground system of lead 253 remains disconnected through the above operation of switch S2.

During rotation of the turret the pawl 34 rides on the periphery of the turret until received by the next notch 33 for the "unloading" position, where switch S7 is thus released to stop the indexing motor. The turret having reached the unloading position, cam block 270 (FIG. 1) effects engagement of the switch S3, thereby extending a ground lead 323 to a manual control switch S20. The operator now removes the stamp coil from the spindle and presses said "Manual Index" switch S20, thereby connecting ground lead 323 to lead 321 for operating the valve V4, so that pawl 34 again disengages from the unload notch and the turret is indexed by the indexing motor until stopped at the winding position. At this point the pawl falls into the slot and the turret and controls are again ready for another cut-off and reset sequence.

Turret safety circuit

The turret safety circuits are arranged to stop the coiler and disconnect it from the press drive if the turret is not in proper position for a cut-off at 100 or 200 stamps before the cut-off is to occur.

The pre-cut-off signal pulse, which occurs either at 100 or 200 stamps before cut-off in accordance with the setting of the pre-signal cut-off selector switch S9, as earlier described operates relay K2 (FIG. 31) momentarily and closes the contacts (1-3) and (6-7) thereof. As heretofore described the contacts 3 and 7 of relay K2 are both connected over lead 272 to the coil of relay K13 (FIG. 31B), while contact 1 of said relay K2 is connected over lead 267 to the normally open contact 269 of the turret winding position switch S2 and contact 6 is connected by said lead 267 to the normally open contact 268 of the turret latch switch S-7. If the turret latch 34 is not properly seated in its notch or if the turret is not in the winding position, then when relay K2 operates, ground is caused to be connected by the respective operated switch arms 271, 273 to lead 267 and/or contacts (6-7) (1-3) of relay K2 and over lead 272 to operate relay K13 and signal lamp L5, which will then be held by holding contacts (1-3) of relay K13.

It will be recalled that the coiler is driven by the press through a clutch/brake unit 36, 36' (FIGS. 11 and 31B) and which drive may be modified to effect corrections by means of jogging operations effected by a motor 40, including a brake means 56 associated therewith. Also, associated with the control circuits for the above drive means is a pair of manual control switch members S12 for the "press drive" and S13 for the "jog drive." For coiling operations the switch S12 will be depressed and will extend ground over a lead 324, normally closed switch S13 and normally closed contacts (5-6) of the relay K13 to energize a pair of relay members K17A, K17B. As will hereinafter be more fully described said relays when in energized condition provide for "press drive" operation and when released will act to transfer the coiler drive from press drive to "jog drive" control. Thus operation of relay K13 above described by opening the contacts (5-6) thereof will cause the coiler to stop and the operator may now correct any error condition by indexing the turret to the winding position through the correction motor 40, as in manner hereinafter to be described.

The turret safety circuit above described remains operated until a suitable reset switch S18 is depressed to remove ground from lead 314 of the holding circuit for relay K13.

Control circuits for the jogging motor

On "press drive," that is with switch S12 depressed, air motor 40, which provides correction and jogging drive to the 1st differential input means in the manner as described with respect to FIG. 11, is automatically controlled by the micro switches S10 and S11 in ac-

cordance with operations of the dancer arm 1 (FIG. 1A) by the input feed of stamp web w.

With the coiler on "Press Drive" and relay 17A operated thereby, air valves V5 and V6 for operating motor 40 are connected over respective leads 325, 326 to the corresponding switches S10-S11, through engagement of related contacts (6A-7A) and (1A-3A) now operated by said relay 17A. A ground circuit extends to the switches S10, S11 over lead 327 and the normally closed contacts (8-11) of a relay K18. Thus if the dancer arm 1 moves far enough downward to close switch S11 circuit over lead 327 is extended thereby to the closed contacts 1A-3A of relay K17A and by means of lead 326 therefrom to valve V6, which thereupon opens to drive the correction motor 40 forward for increasing the winding speed of the coiler. If the dancer arm moves too far upward, then switch S10 will close and circuit from lead 327 now goes through closed contacts 6A-7A of relay K17A and over lead 325 is extended to valve V5 for a reverse operation of the motor to slow the coiling speed down.

As above described the ground circuit for the operations of valves V5 and V6 for the correction motor 40 extends through the contacts (8-11) of a relay member K18. Said relay is connected by means of lead 328 to normally open contacts (9-11) of the relay K3 (FIG. 31). As earlier described relay K3 will be operated at either 200 or 100 stamps before the cut-off, thus at that time contacts (9-11) of said relay are closed and circuit lead 328 is extended thereby to the number (3) tap on the tends decade readout switch of the counter S1. Upon the next sweep of wiper arm 257 across said tap, ground from lead 259 to lead 328 will operate relay K18 which will thereupon open the related contacts (8-11) thereof and thereby remove the control ground 327 from the described circuits for motor valves V5-V6. This stops the operation of the correction motor 40 a few press impression of stamps before the cut-off and thereby insures that any slight correction change in the coiling speed as introduced by the correction motor operation will not occur at this time and affect the accuracy of the cut-off.

The coiler may be placed on manual jog drive by depressing switch S13 (FIG. 31B) which thereupon opens ground lead 324 and releases the relay members K17A-K17B. Release of relay K17A restores contact 6A from contact 7A to engage contact 5A and at the same time will release contact 1A from contact 3A to engage contact 4A of said relay. Thus valves V5 and V6 are now connected to the respective manual switch members S15 and S16 for manual control operations of the motor 40 to jog the coiler in a reverse or forward direction, as by the following circuits.

The forward jog button S16 when depressed picks up ground lead 327 from the normally closed contact 329 of the dancer up limit switch S10 and extends the circuit through contacts (1A-4A) of the relay K17A and lead 326 to the valve V6 to drive the coiler in the forward direction. If the coiler is webbed up and if the forward jog is operated until the dancer arm 1 (FIG. 1A) operates the up limit switch S10 free of contact 329, then the above ground circuit to valve V6 will be broken and the coiler cannot be jogged any further in the forward direction. This feature prevents forward jogging to the point of tightening up on the web until it breaks.

As previously described, a brake 56 (FIG. 11) is attached to the output shaft 55 of the correction motor 40. The purpose of the brake being to prevent drifting of the shaft 55 under influence of the first differential when the correction motor 40 is not running. This brake is electrically actuated under the control of a relay K26 and potentiometer R22, as will now be described.

Relay K26 is a DC relay and its operating coil is connected to the leads 325 and 326 for the valves V5 and V6 respectively. When neither valve is operated the input potential on leads 325, 326 are equal so there is no

operating voltage across the coil of relay K26. When one or the other of valves V5 or V6 is operated, for example valve V6, then its control (lead 326) is completed to ground as above described. Thus also the corresponding terminal of the relay K26 is also connected to ground. At the same time an opposite terminal of relay K26 is connected to the 115 v. AC supply at 330, through the operating coil and series rectifier of the valve V5. Thus the operating coil of relay K26 has rectified DC current flowing through it and said relay operates. Upon operation of relay K26, ground circuit through contacts (1-4) thereof and lead 331 extending to the brake 56 associated with jog motor 40 is opened and said brake is released.

Thus whenever one or the other of the control valves V5 or V6 for the correction motor is operated the brake 56 releases and the shaft 55 of motor 40 is free to rotate. When both air valves V5 and V6 are closed however relay K26 is released, the brake 56 receives field current through resistor R22 and the motor shaft 55 is prevented thereby from turning.

Press and jog drive control circuits

As earlier stated the coiler drive is transferred from press drive to jog drive in accordance with operations of a pair of relays K17A and K17B as determined by the respective setting of associated manual control buttons S12 and S13. The principal function of relay K17B is to control the electric clutch-brake unit 36-36' (FIGS. 11 and 31B) on the ninput shaft 35 of the coiler. When the coiler is to be driven by the press the clutch 36 must be operated and when the coiler is transferred to jog drive the brake unit must be operated to hold the input shaft 35 fixed so that the correction or jog motor 40 can effect operations of the first differential, in the manner heretofore described.

The brake and clutch units 36'-36 have identical circuits, each under control of respective relays K21 and K22 and which in turn are each under control of the ground contact arm (11B) operated by the relay K17B. With the press drive key S12 in raised position, ground over lead 324 to relay K17B is off and said relay therefore is in de-energized condition. In this case contact arm 11B engages contact 8B, as shown, and ground being extended by means of lead 332, the relay K21 for brake 36' is in energized condition. Said relay when energized closes at successive intervals first a contact bridging member 333 and then a bridging member 334 associated therewith to extend ground first by means of lead 335 to apply a first step of energy at a lower level current through suitable resistors R7, R8 to the brake member 36' and thereafter a higher level current through the delayed contact lead 336.

With the coiler in press drive, by operation of key S12, relay K17B displaces its contact arm 11B from contact 8B to contact 9B, thereby releasing relay K21 and the brake circuits associated therewith, while energizing relay K22 to successively close first contact bridge 333' and then contact bridge 334' for operating clutch 36 as in the manner above described for brake 36'. In operation, when the coiler is transferred to "press drive" the instant contacts 333' will close first for applying a lower level of clutch current through resistors R5 and R6 to lead 335'. The clutch does not develop full torque with this field current and therefore slips as it brings the coiler load up to speed. At a suitable later time when the coiler is almost at press speed the delay contacts at 334' close, thereby through lead 336 shorting out the starting resistor R5 and applying full field current to the clutch 36.

The delay time of the delayed contact means 334, 334' may be adjusted by the usual well-known suitable screw adjustment means therefor.

Slitter mandrel start-up circuit

It is recalled that the slitter mandrel 17 (FIGS. 1 and 75

6) is given extra torque at start-up to overcome the starting friction of the slitter knives 16. The following circuits provide for such extra start-up torque.

As earlier set forth valve V19 (FIG. 31A) and air regular valve V18 control the air applied to the slitter mandrel air clutch 187 on startup. When the coiler is stopped, valve V19 opens and a higher air pressure than the normal running air pressure is applied to the clutch. The regulator valve V18 controls this starting air pressure. 5 As the coiler starts to move, this higher starting air pressure is maintained for one half a revolution of the slitter mandrel 17. The higher startup air pressure is then removed by the closing of valve V19 and the slitter mandrel clutch air pressure thereupon returns to the normal running valve V17.

10 Valve V19 is controlled by a relay string consisting of relays K23, K29 and K30. With the coiler in stopped condition, said relays are all deenergized and a pair of normally closed contacts (5-8) of relay K30 will extend ground over lead 337 to valve V19, holding said valve in operated condition.

15 As the coiler begins a movement and relay K23 makes its first closing, contacts (1-3) thereof connects ground over lead 338 to the coil terminal of relay K29. The other terminal of relay K29 is connected to positive 135 volts D.C. lead 339 through 1 mfd. condenser C10. The charging current for condenser C10 through the relay coil K29 causes relay K29 to operate for momentarily closing its contacts (1-3). Closing of said contacts connects ground 20 lead 340 to 100 mfd. capacitor C11 charging it through a resistor R26 and also applying full 135 volts D.C. to the relay K30. Relay K30 thereupon operates and opens contacts (5-8) thereof causing valve V19 to close and remove the start-up air pressure off the slitter clutch 188. Mean- 25 while relay K29 releases and thereby opens the charging circuit contacts (1-3) thereof. However, relay K30 re- 30 mains operated, due to the capacitor C11 discharging through its coil and will remain operated until the capacitor charge drops to approximately 75 volts. Before the 35 voltage drops to said level, however, another closure of relay K29 will occur to recharge capacitor C11. Thus as long as the coiler continues running the capacitor keeps re- 40 charging, relay K30 remains operated and the valve V19 remains closed.

45 When the coiler is stopped, recharging of capacitor C11 will stop and its charge drains off through the coil of relay K30. When the charge drops below the critical voltage relay K30 is released closing its contacts (5-8), thereby reopening valve V19 and reapplying the starting air 50 pressure to the slitter mandrel clutch 188.

The critical charge voltage is reached and relay K30 released approximately five seconds after the coiler is stopped.

55 All relays with the exception of relays K21, K22, K26 K27 and K28 are three pole double throw relays of well-known circuitry, such as illustrated in FIG. 31C. Relays K26, K27 and K28 are double pole double throw relays of a known circuit, such as shown in FIG. 31D.

While there has been shown and pointed out the fundamental novel features of the invention as applied to a preferred embodiment thereof, it will be understood that various omissions, substitutions, and changes in the form and details of the devices illustrated and in their operations may be made by those skilled in the art, without departing from the spirit of the invention. It is therefore to be limited only as indicated by the scope of the following claims.

What is claimed is as follows:

1. Apparatus for winding predetermined lengths from a continuously moving web, comprising in combination 70 a support frame; a web winding mandrel rotatably supported thereon; a drive train for advancing a web from a take off roll planetary gearing driven by said drive train and having an output train therefrom for operating said mandrel

a control input train for said differential, having independent power means therefor; and means operable by a web for determining direction and extent of operations of said control train whereby to control the output train of said differential gearing and thereby synchronize operations of said mandrel with said drive train.

2. Apparatus for winding predetermined lengths from a continuously moving web comprising in combination a rotatable frame; a plurality of web winding mandrels rotatably supported thereon; an operating input drive for said apparatus and for advancing a web; web take up means adapted for converting intermittent movements of a web by said drive to continuous movement of a web by said mandrels; planetary gearing having one train connected for continuous operations by said input drive and an output train connected to said winding mandrels; control input train for said differential including independent power means; and control means for said power means, operable by the web take up means to determine direction and extent of operations of said power means, whereby said output train of said differential maintains operations of said winding mandrels synchronized with operations of said input drive.

3. Apparatus for winding predetermined lengths from a continuously moving web, comprising in combination a rotatable turret adapted for indexing to selected positions; a plurality of web winding mandrels rotatably supported thereon; a drive train for said mandrels including a first differential means thereon; an input control train for said differential having independent power means therefor; control means for said power means operable by an incoming web whereby to regulate operations of said differential and thereby said mandrel to synchronize with the speed of said incoming web; a second differential in the mandrel drive train and including an input train driven by the output train of said first differential; a power train for rotating the turret supporting said mandrels; and said second differential including a control input train operable by said turret power train for compensating operations of the first said input train according to any turret movement, whereby operations of said mandrel are uniform to both turret and non-turret operations.

4. The invention according to claim 3 including a pair of shafts operable by the said second differential; a two part drum mounted on each of said shafts each drum having a first part loose thereon and a second part fast for rotation with the respective shaft; a fixedly mounted brake shoe maintaining the said first parts of said drums against rotation; a ball/plate integrating means between the said drums and the respective web winding mandrels; and means operable by a web as the coil size increases for controlling said integrating means whereby to decrease the mandrel speed in direct proportion to the increase of web surface speed as the coil size increases.

5. The invention according to claim 4 and means operable in a movement of the turret to a given position for displacing the active ball/plate integrating means from the said rotating part of said drum to the said fixed part thereof and thereby stopping operation of the related mandrel.

6. A coiling machine for winding and cutting predeter-

mined lengths from a continuously moving web, comprising in combination

- a rotatable frame; a plurality of web winding mandrels rotatably supported thereon; an initial drive means providing an infeed movement of a web to said coiling machine; a plurality of planetary gearing devices having interconnecting output trains connecting said initial drive means with said mandrel; a control train associated with a first one of said planetary gearing devices and adapted for synchronizing rotation of said mandrels with said initial drive means; web cut off means operable by a second one of said planetary gearing devices; integrating gear means operable by the said first planetary devices for modifying an output speed of the second planetary devices; control means for said integrating means, adapted for operation by a third one of said planetary devices; and means operable by movement of a web for modifying the operations of said third differential gear train, whereby operation of said web cut off means by the said second planetary gearing devices is synchronized with a movement of a web.

7. Apparatus for winding and cutting predetermined lengths from a continuously fed web, comprising in combination

- a rotatable turret including spaced end plates having opposed first guide tracks therein; a plurality of web winding mandrels rotatably supported upon said turret; spaced stationary frames having opposed second guide tracks therein normally forming a continuation track to said first guide track; web severing means mounted for movement in said tracks; and operating means for effecting a reciprocatory movement of said web severing means along said guide tracks whereby to effect a web cut-off during a winding of a web upon a given one of said mandrels.

8. The invention according to claim 7 including a drive train for said mandrels comprising a plurality of differential gearing devices including a first differential connected to an input drive shaft; a second differential including an input train driven by said first differential;

- a second input train for said second differential, including a variable speed integrator therein driven by said first differential; said second differential having an output train for operating said operating means for said web severing means; and

- control means including an oscillating arm for controlling output speeds of said integrator, whereby to modify operations of said output train of said second differential and thereby synchronize operations of said web severing means with operations of said mandrels.

9. The invention according to claim 8 and a third differential gearing, said third differential having an input train operable by said output train of said second differential, an input train operable by the surface movement of a web and an output train adapted for effecting oscillating operations of said control means in accordance with any variations as occur between said input trains.

10. The invention according to claim 9 and including a pin cylinder engageable with spaced perforations of said web in effecting said operations of the second said input train for said third differential.

11. The invention according to claim 9 and a third input leg for said third differential including manually operable means therefor adapted to advance or retard the

timing phase for the operations of said control means by said third differential.

12. The invention according to claim 9 and wherein the said operating means for said web severing means include a follower arm and a face cam embodying a circular cam track for guiding a non-operation of said follower arm and a developed cam track for imparting a positive reciprocatory movement to said arm and thereby said web severing means in exact synchronism with a movement of said web.

13. The invention according to claim 12 and in which said developed cam track is designed to accelerate said web severing means up to web surface velocity in a first portion of movement thereof prior to engagement of said severing means with said web and thereafter to operate the severing means at web speed throughout severing contact thereof with a web and following severing of a web to decelerate the cut-off means then reverse and restore the web severing means to its starting position.

14. The invention according to claim 13 and control means adapted for automatically controlling a displacement of said follower arm from the control of one said cam track to the control of the other said cam track.

15. The invention according to claim 7 and in which the said web cut-off means include

a plurality of interconnecting chain links engaging said guide tracks for movement therein;
a plurality of bars extending transversely of a web path and secured each at their opposite ends with a corresponding one of said links; and
a cut-off knife fast with the leading one of said bars and adapted in a forward stroke movement guided by said track to engage and independently effect a web severing operation.

16. The invention according to claim 15 and said first and second guide tracks forming continuous tracks during cut-off operations.

17. The invention according to claim 16 and in which said first tracks substantially encompass the pivotal support for said mandrels.

18. The invention according to claim 17 including spring biased pressure rollers on shafts yieldably mounted in each of said transverse bars, said rollers adapted during a movement of said bars along said tracks to press a web against the peripheral diameter of said winding mandrel and maintain tension upon a web during web severing operations.

19. The invention according to claim 18 and a plurality of spring tempered fingers secured to the terminal one of said bars and extending therefrom to underlie the pressure roller shafts;
a follower arm having a roller engageable with said web mandrel; and
wherein the distal end of said fingers in an operation of said bars around said mandrel are forced by the individual pressure roll springs forwardly of said cut-off knife for guiding the incoming severed end of a web into the nip between said mandrel and the said follower roller.

20. The invention according to claim 19 and spring guide fingers extending from said follower arm to further guide a web into said nip between an oncoming web and said mandrel.

21. Apparatus for winding and cutting predetermined lengths from a continuously moving web, comprising in combination

a rotatable turret for indexing to successive control positions;
a power train for indexing said turret and adapted for selective operation;
a plurality of web winding mandrels rotatable upon said turret and displaced therewith to said successive control positions;

a power train continuously operable for rotating said mandrels in web coiling operations;
differential gearing in common to both said power trains and adapted upon an operation of said turret power train during web coiling operations to modify the movement of the said continuously operable power train to compensate for any web movement effected by said turret indexing operations.

22. The invention according to claim 21 and in which said web winding mandrel comprises two sections each with a cooperating cam surface biasing substantially the longitudinal length thereof; and

wherein one of said sections is mounted for slidable movement upon the other along said cam surfaces; said sections together normally forming opposed circular segments of a given diameter; and means operable upon operation of said turret to a given indexed position for displacing the slideable section along said cam surfaces and thereby reduce the diameter of said segments, whereby the provide easy web removal by releasing frictional engagement of said mandrel from a web coiled thereon.

23. The invention according to claim 22 and in which the means for displacing the said slideable section includes an operating member pivoted upon said turret and provided with a cam follower roller; and

a fixed cam member engageable by said roller for operating said member as said turret is indexed to a given position for unloading a web coil.

24. The invention according to claim 1 and having slip clutch means for producing a controlled drag on a web including,

first friction devices in said clutch rotatable by said differential drive for the web winding mandrel;
second friction devices in said clutch for cooperation with the first said friction devices; and
wherein said second friction devices are rotated by a web at greater speed to that of the first said friction devices for maintaining slipping friction therewith.

25. The method of coiling a roll having a predetermined number of designs or indicia from a continuously supplied web having a succession of designs or indicia thereon, which comprises the following steps

determining the predetermined number of designs or indicia desired to form the roll;
coiling a roll from the continuously supplied web;
counting the number of designs or indicia coiled into the roll;
initiating a web severing operation prior to completion of the count to said predetermined number;
synchronizing said web severing operation with movement of the web; and
without arresting movement of the web completing said web severing operation so as to sever the web following the design or indicia of predetermined number and before the next succeeding design or indicia on the web.

26. The method of claim 25 including the step of coiling the roll upon a mandrel.

27. The method of claim 26 including the steps of providing a second mandrel upon which the web is also to be coiled;
driving said second mandrel at a speed corresponding to that of the moving web; and
performing said severing operation at a point between said mandrel and said second mandrel.

28. The method of claim 27 including the steps of pressing the web against said second mandrel as a part of said severing operation and starting a new roll thereon.

29. The method of claim 28 including the step of enveloping said second mandrel with a free end of the web to bring the leading edge thereof with the design or indicia subsequent to the severed one into nip with the oncoming web.

30. The method of claim 28 including the steps of mounting said mandrels on a movable support; moving the mandrels and support in a predetermined manner during the coiling operation; collapsing the mandrel from a first size to a second size during said movement of said support to facilitate removal of the coil therefrom; removing the coil from the collapsed mandrel; and expanding the mandrel during a subsequent movement of the mandrel and support.
31. The method of claim 30 including the step of maintaining a constant uniform movement of the web during movement of the support.
